WINDING MACHINE

James C. Anderson, deceased, late of Elmhurst, N. Y., by Annie G. Anderson, executrix, Elmhurst, N. Y., assignor, by mesne assignments, to Alcat Electro Products Corporation, New York, N. Y., a corporation of Delaware

Application April 7, 1926, Serial No. 100,319

Renewed July 29, 1936

33 Claims. (Cl. 242—10)

This invention relates to machines for winding strands of material, such as wire, thread, ribbons or filaments into coils, helices or bobbins, and has special reference to machines for winding copper wire into electrical coils or helices for use in various kinds of apparatus. The particular invention herein described is an improvement upon machines described in U. S. Patents No. 654,583 issued July 31, 1900, and No. 798,864, issued 5 September 5, 1905, with particular reference to the latter. In the patented machines mentioned, a plurality of coils are wound simultaneously, in separated zones, upon a spindle or mandrel, the convolutions of wire being wound in layers superimposed one upon the other and the machine being adapted to introduce or inject sheets of paper between the adjacent successive layers during the building-up of the coil and while the spindle is in motion. Each layer in all of the coils is finished 10 at the same instant, and at that instant a sheet of paper, of sufficient length to make one or more complete wrappings around each coil and of sufficient width to extend over all of the coils on the spindle, is delivered to the spindle and wound thereon as a foundation for the next succeeding 15 layer. When the required number of layers are completed the machine stops and all of the coils on the spindle are removed in a body or "stick" which is afterward separated into individual coils 20 by severing the various layers of paper between 25 the spaced coils.

The object of this invention is to provide a simplified general purpose strand winding machine which is readily adaptable to a wide range of 30 work.

Among the improvements of the present invention over the aforementioned patented machines is the manner in which the paper is handled and introduced between the layers of the coils. The 35 paper serving mechanism of the present invention comprehends a new and more desirable cycle of events, whereby the simultaneous winding of a comparatively large number of coils is effected by providing mechanism capable of feeding to the 40 spindle, successive sheets of paper of sufficient width to cover the comparatively large number of coils on the spindle, and to inject those sheets into the coils and wind them thereupon evenly and smoothly without diminution of the spindle speed 45 to furnish individual foundations for the respective layers of wire. Means is also provided whereby a plurality of different sources of sheet material supply is furnished, any one of which may be readily selected during and without interrupting the winding process. For example, the 50

first and last few layers of all of the coils of a winding can be served, if desired, with heavy paper, oiled linen, silk, or the like, and the intervening layers may be served with an insulating paper adequate for the purpose, which is accomplished selectively while maintaining the spindle speed, without wrinkling the sheet layers or producing other irregularities therein, notwithstanding the fact that exceedingly thin paper may be used.

Another improvement over the aforementioned 55 patents, particularly No. 798,864, is the replacement of the reciprocating slide, carrying the knife and paper feeding devices, by a pair of light oscillatory pivoted paper carrying arms 15 which draw the paper over a support or platen and operate in conjunction with a severing and measuring mechanism to serve smoothed sheets of the proper size to a paper ejecting mechanism which thereafter inserts the sheets into the grip 20 of the strands being wound upon the revolving spindle. More specifically, the paper gripping fingers, at the extremities of the pivoted arms, grasp the lateral margins of the paper web near the forward edge and effect a slight lateral motion and draw it taut on the support or platen as well as along its forward edge, feed an automatically measured length of the web through a relatively stationary knife, pause while the sheet 25 is severed from the web by the knife, resume the feed, and deliver the sheet by transferring its forward edge to the ejector mechanism, whereupon the lateral gripping fingers are immediately rapidly retracted, the sheet being supported on and constrained to the surface of the platen by 30 independent pressure members as well as by gravity instead of being solely suspended from one edge and otherwise left free to obtain what support is within reach. Accordingly, smooth and efficient operation is obtained within a small compass, whereby the friction, inertia, and momentum 35 of the massive reciprocating slides of former machines is eliminated, as well as much of the size and cost of the machines.

The mechanism for feeding the strand material, 45 such as wire, is substantially the same as that disclosed in aforementioned Patent No. 798,864, as well as the wire feed reversing mechanism, whereby the successive layers of wire are wound at the proper predetermined length with a reciprocating movement upon each other and severally along the spindle in the usual manner, with the addition of a selective mechanism for automatically contracting the length of each successive 50 layer in order to make another type of finished coil 55

if desired. The arrangement of the wire supply spools and the tensioning mechanism, with reference to the coils being wound, is superior to the previous types of machines in that all of the 5 wire on and passing from all of the spools is directly visible to the operator standing in front of the machine, and in that all of the spool axes are very nearly horizontally arranged to avoid snarling when unwinding, the slight angle to the 10 horizontal being only of such an amount and direction to prevent the spool from falling or flying off of its arbor should the spool locking devices suddenly fail, and the spools, being mounted on overhung arbors, are accordingly readily taken 15 off and replaced from the sides of the machine without interfering with the neighboring spools or the strands of wire passing therefrom to the winding spindle.

By utilizing a trunnion-pivoted carriage, the 20 machine is adaptable to wind a wide range of coil diameters, and the driving mechanism includes gearing and pulleys that can be selectively engaged to drive the winding spindle at the requisite speeds consistent with the diameter and character 25 of coils to be wound. For example, in winding relatively small diameter coils, belt driven cone pulleys are utilized whereby relatively higher speeds are attainable with comparative silence and negligible vibration, and in winding heavier 30 wire and larger coils, for which slower speeds and greater power may be necessary, intermeshing spur gear combinations are provided. In order to eliminate the complication attending the utilization 35 of a plurality of cam-operated friction clutches, the present machine employs only one friction clutch in conjunction with several small jaw clutches, which latter are liable to but little wear, and consequently need very rarely if ever to be replaced, whereas friction clutches need 40 periodic attention for adjustment, relining and the like.

A back-winding system is provided on the present machine, which resembles that described in aforementioned Patent No. 798,864, whereby the 45 arbors of the wire supply spools are driven by the winding spindle mechanism in a direction opposite to that which they are revolved by the unwinding of the wire as it is being drawn off of the spools and wound upon the winding spindle. Accordingly, by manually effecting the clutching of 50 reversing gears in the present machine, the winding spindle and the spools are dependently driven in a reverse direction to unwind wire from the winding spindle and to rewind it upon the several spools, in order to return the machine to a prior 55 position in the winding process for the purpose of mending a broken strand, replacing an exhausted spool, or the like.

The particular nature of the invention as well 60 as the objects and advantages thereof will appear more clearly from the following description of a preferred embodiment as illustrated in the accompanying drawings, in the several views of which like reference characters designate like parts.

65 In the drawings:

Fig. 1 is a front elevation of the coil winding machine;

Fig. 2 is a plan view thereof, with the spool frame removed;

70 Fig. 3 is a side elevation of the machine shown in Fig. 1, the upper portion of the spool frame being broken away;

Fig. 3a shows a continuation, in side elevation, of the broken away spool frame of the preceding 75 figure;

Fig. 4 is a perspective view of the main drive and associated shafting and other parts, as viewed from the rear of the machine from the normally right hand side thereof toward the center;

Fig. 4a is complementary to Fig. 4 and shows the continuation of the main drive and allied shafting to the normally left hand side of the machine;

Fig. 4b is complementary to Fig. 4 and shows the interchangeable gears for changing the back- 10 winding speed;

Fig. 5 is a plan view showing associated shafts in a drive in which the ratchet mechanism is included;

Fig. 6 is a detail view of a ratchet drive; 15

Fig. 7 is a vertical section showing the internal arrangement of the parts of the right hand side of the machine;

Fig. 8 is a similar view, but shows the parts on the left hand side of the machine; 20

Fig. 8a is a complementary view to Fig. 8 showing the paper ejecting actuating mechanism;

Fig. 9 is an irregular generally vertical section through the right hand side of the machine, the paper conveying arm having been arbitrarily 25 moved into its upper position;

Fig. 10 is a corresponding view through the left hand side of the machine;

Fig. 11 is a detail view showing an oscillatory lever, partly in section, which is included in a 30 linkage which is operable to shift the cams in the cam housing;

Fig. 12 is a perspective view of the upper end of one of the paper carrying arms, showing the relation of the stationary and movable fingers; 35

Fig. 13 is a fragmentary vertical section through the cams and cam housing that are attached to the right hand wall of the carriage frame;

Fig. 14 is a detached view showing the switch cam and the parts which coact therewith; 40

Fig. 15 is a detached view of the knife cam;

Fig. 16 is a similar view of the gripper cam;

Fig. 17 is a rear elevational view of the lower portion of the machine, as viewed in the direction of the arrow A in Fig. 7; 45

Fig. 18 is a fragmentary projection of the lower portion of the mechanism shown in Fig. 7, as viewed in the direction of the arrow B;

Fig. 19 is a view of one of the paper shield plates of the switch mechanism;

Fig. 20 is a similar view of another of such shields; 50

Fig. 21 is a like view of one of the supplementary guide plates which is associated with each of the shields;

Fig. 22 is another such auxiliary guide plate, such as is centrally positioned with respect to the shields; 55

Fig. 23 is a fragmentary front elevational view of the carriage, showing in its upper portion means for adjusting the ejector plate, said view also showing in its lower portion a supporting bar for the paper shield spiders;

Fig. 24 is a sectional detail showing means for adjusting the fulcrum of a feed actuated arm; 60

Fig. 25 is a sectional detail of a clutch associated with a shaft which is adjustable with respect to a number of layers in a prescribed coil;

Fig. 26 is an irregular section through the head stock, a portion of the exterior of the latter being shown in elevation;

Fig. 27 is a view taken at right angles to head stock as shown in Fig. 26, certain of the parts being broken away for improved clearness; 75

Fig. 28 is principally a section through the tail stock;

Fig. 29 is a view of the tail stock as seen at right angles to the view in Fig. 28, portions being 5 in section;

Fig. 30 is a detailed section showing a modification of the tail stock center;

Fig. 31 is a sectional detail view of locking means for the tail stock;

10 Fig. 32 is a plan view of the spool frame, showing in dotted lines the rewinding mechanism for the spools;

Fig. 33 is a detail view of a part of the rewinding mechanism showing the grouping and unification of certain gears;

15 Fig. 34 is a longitudinal section illustrating certain braking mechanism associated with individual spools;

Fig. 35 is an end view of the braking mechanism; and

20 Fig. 36 is a diagrammatic view, in perspective, showing the pitch circles of the gears in the rewinding mechanism together with shafts that connect various gears.

25 Referring to the drawings, and particularly to Figs. 1 and 3, numerals 1 and 2 designate the standards comprising the pedestal which supports the bed plate 3 of the machine. The power is furnished by a motor 4, as illustrated in Fig. 3, 30 or any other driving means, which, by a belt 5 drives clutch pulley 6 freely upon shaft 1 which is suspended from the rear of bed plate 3 by means of hangers 8 and 9, as is most clearly illustrated in Figs. 4 and 4a. In order to drive shaft 1, starting handle 10, at the front of the machine, is thrown downwardly to turn clutch shaft 11 and lever 12 so as to move collar 13 in its keyway along shaft 7 to effect the engagement of clutch band 14 with clutch pulley 6, which accordingly 35 drives pulley 6, since band 14 is pivoted on clutch slide 15 which is keyed to shaft 7. As handle 10 is thrown downwardly into the clutching position shown in Fig. 1, coil spring 16 is tautened and the pawl 17 of trip handle 18 engages an 40 angular extension 19 upon handle 10 which locks 45 it in clutched position. Accordingly when it is desired to declutch the machine from the power, it is only necessary to strike trip handle 18, whereupon its pawl 17 releases clutch handle 10, which 50 is thrown upwardly against stop 20 by spring 16 to release clutch pulley 6 and stop the machine.

55 A normally closed jaw clutch 21, keyed to shaft 7, rotates bevel pinion 22 which drives bevel gear 23 and shaft 24 which is journaled in hanger 8, as is illustrated in Fig. 4. A worm 25 is mounted on the other end of shaft 24 which rotates worm wheel 26 and consequently shaft 27 which is journaled on top of bed plate 3, as shown in Figs. 2 and 3. Referring to the enlarged views of Figs. 60 5 and 6 of the ratchet driving mechanism mounted on top of bed plate 3 in brackets 28 and 29, it will be seen that shaft 27, by virtue of ratchet 30, can only drive pinion 31 in one direction, namely in a counter-clockwise direction as 65 viewed in Fig. 6, since the ratchet teeth in wheel 32 are arranged so that pawl 33 engages them only when driven in that direction and is disengaged when pinion 31 is rotated in the opposite direction. It may be noted that the ratchet 70 is only utilized when hand-wheel 36 is revolved when the machine is idle. Pinion 31 drives gear wheel 34, which is keyed to a short shaft 35, as is hand-wheel 36, the other end of shaft 35 being formed with an integral disc 37 which constitutes 75 the driving element of a slip coupling 38, which

drives a coaxial shaft 39 through friction washers 40, which engage disc 37 and accordingly actuate member 41 pinned to shaft 39, as illustrated in Fig. 5. A coil spring 42 maintains the proper pressure of washers 40 upon disc 37. By means 5 of two universal joints 43 and 44, and two short shafts 45 and 46 connected to shaft 39, a pinion 47 is driven, which is journaled in right hand side frame 48.

The two side frames 48 and 49, illustrated in 10

Figs. 7 and 8, respectively, are suspended in a

space in the center of bed plate 3, being mov-

ably trunnioned upon shaft 50, which is mounted

on brackets 51 and 52 secured upon and near the

rear edge of bed plate 3. Referring again to Fig. 15

7, it will be seen that pinion 47 meshes with and

drives gear 53 in a counterclockwise direction

freely upon shaft 54, and which in turn drives

gear 55 in a clockwise direction. A roller 56, at-

20 attached near the edge of gear 53, moves in a recti-

linear groove in lever 57, which accordingly oscil-

lates about pin 58 as roller 56 describes its circu-

lar orbit and carries lever 57 with it. The lower

end of oscillatory lever 57 is provided with a

25 toothed sector 59 which meshes with a pinion 60

causing it to periodically reverse in direction of

rotation as it is driven by oscillating sector 59.

Upon examining Fig. 9 in conjunction with Fig. 7,

it will be seen that pinion 60 rotates freely upon

a short shaft 61 and that embracing and rigidly

30 pinned to it is a hub 62, which is illustrated as

an enlarged plan view in Fig. 11. Hub 62 is pro-

vided with a slotted radial extension 63 having a

pair of opposed ears 64 at its base between which

is fulcrumed a double lever 65, the surface of the

35 upper arm of which is bevelled, as shown in Fig.

11, and coacts with a similarly bevelled T-shaped

lug 66 rigidly secured on lever 67 which is mount-

ed freely upon the hub of pinion 60. Accordingly,

upon the engagement of lever 65 with lug 66, a

40 wiping cam effect is produced which causes lever

65 to pivot about its fulcrum in hub 62, which

movement is constrained by pin 68 and spring 69,

and consequently lever 65 effects the movement of

pin 70 longitudinally for purposes to be ex-

plained hereinafter.

The rotation of pinion 60 turns the hub of

pinion 60, the hub 62, the extension 63 of the

latter and pin 71 on 63, which is engaged by a

spring-pressed hook latch 72 pivotally mounted

50 on arm 73, and so causes the rotation of arm 73

which is pinned to shaft 61 as illustrated in Figs.

7 and 9. Inasmuch as tubular shaft 74 is like-

55 wise pinned to shaft 61 and arm 73, and as the

arms 73 and 75 are joined by tubular member

76, a simultaneous motion is imparted to shaft

71 and arm 75 which are similarly mounted as

illustrated in Fig. 10, the complement of Fig. 9.

For purposes of clarity, arms 73 and 75 are

shown respectively in a different position in Figs. 60

9 and 10 than that in which they are shown in

Figs. 7 and 8. Arms 73 and 75 each terminate in

a relatively stationary member 78 which is

shaped as shown most clearly in Fig. 12 and is

provided with a flat finger 79. The outer ends

65 of arms 73 and 75 terminate in integral plates

80, each of which has a portion of reduced thick-

ness, whereby a shoulder is formed longitudinally

of the plate 80, as at 80a in Fig. 12. To the por-

tion of reduced thickness of each plate 80, a

70 bent portion of the stationary member 78 is se-

cured, so that it is parallel to but spaced from

the shoulders 80a. A retaining plate 80b, which

is shown broken away in Fig. 12, lies against a

face of the thicker portion of the plate 80 of 75

arms 73 and 75, and, as shown in dot and dash lines in Fig. 12, has a width approximating that of plate 80, the retaining plates 80^b being secured by screws 80^c to the plate-like termini 80 of the arms 73 and 75. Thus, the stepped plate 80 of each of these arms, the portion of stationary member 78 that parallels the shoulder 80^a, the shoulder itself and the retaining plate 80^b form a guide-way in each of the arms 73 and 75. In these guide-ways, radially movable members 81 and 82 are respectively provided, each of which terminates in a finger 83 disposed in juxtaposition to and adapted to coact with finger 79, which is rigidly secured to its associated arm 73 or 75. The end of finger 83 is provided with a friction block 84, which is pivotally and eccentrically mounted so that the closure of fingers 79 and 83 causes a lateral force component to move the block 84 in a lateral direction as the fingers 79 and 83 come together, and a consequent relative movement is produced between the coacting surface of block 84 and flat finger 79. The lower extremity of slidable member 81 is pivoted to one end of a lever 85, the other end of which embraces and is pinned to the end of tubular bar 76, and a rigid stud 81^a is mounted on the left-hand slidable member 81 only. Coil springs 86, one end of each of which is respectively attached to members 81 and 82 and the other respective ends to arms 73 and 75, tend to force the closure of fingers 79 and 83 which, however, is normally prevented by the angular position of bar 76 except at certain definite times, which are to be disclosed hereinafter.

Acting against the tension of springs 86 in order to hold fingers 79 and 83 apart during certain periods in the cycle, a spring-pressed curved pawl 87 engages a notch in slidable member 82 of arm 75, as is shown in Figs. 8 and 10, pawl 87 being pinned to one end of a short shaft 88 journaled in a tubular bearing 89 mounted integrally with arm 75, and a cam pawl 90 being pinned to the other end of shaft 88. Freely rotatable upon tubular shaft 74 is a lever 91, held in place upon shaft 74 by a collar 92, and which bears a spring-pressed latch 93 which has the same axial location as pawl 90 and is adapted to engage therewith when arms 73 and 75 are in a certain angular position. Accordingly, as illustrated in Fig. 8, a certain definite angular movement of arm 75 away from lever 91, causes latch 93, which is then engaged with pawl 90, to restrain the movement thereof, and since pawl 87 is attached to the same shaft 88 as pawl 90, it is moved away from slidable member 82, whereupon the latter is immediately retracted by spring 86 to close fingers 79 and 83 upon the lateral edges of a web of paper or other sheet material which is disposed so that the two pairs of fingers 79 and 83 embrace its lateral edges, but do not grip them until pawl 87 is released as above described. Inasmuch as both slidable members 81 and 82 are attached through levers 85 to common shaft 76, they operate in unison, and, by the constraint of springs 86, fingers 79 and 83 of both arms 73 and 75 are closed simultaneously and stretch the paper laterally between them by the lateral sliding movement of members 84 upon fingers 79. The lever 91 has an additional purpose which will be explained hereinafter.

A pinion 94 is pinned to shaft 77 and meshes with a gear 95 journaled on a stud 96 fixed in side frame 49, and gear 95 in turn meshes with pinion 97 adapted to rotate freely on stud 98, 75 and which is fixed to and actuates counterweight

99 for the purpose of counterbalancing the moving masses of the reciprocating arms 73 and 75 and their complemental parts. Shafts 61 and 77, which are rigidly joined to tubular shaft 74 and to arms 73 and 75, respectively, are journaled on studs 100 and 101 in side frames 48 and 49, respectively, as illustrated in Figs. 9 and 10.

Having considered the condition where the arms 73 and 75 have been moved through a sufficient angle, by arc 59 and pinion 60, so that the subsequent release of pawl 87 from its notch in slidable member 82 allows springs 86 to effect the closure of gripping fingers 79 and 83, the arms move freely through an arcuate path until the angular surface of pivotal lever 65, which moves with arm 73, engages the corresponding angular surface of relatively stationary member 66 with a wiping cam effect, whereupon a rocking movement is imparted to lever 65, as heretofore explained. The movement of lever 65 causes the lower portion thereof to exert an axial thrust which is imparted to pin 70, slidably mounted in bearing stud 100, which thrust effects the movement of lever 102, which is pivoted about a fulcrum plate 103 attached to side frame 48, as is illustrated in Figs. 7 and 9. Referring now to Figs. 7 and 13, it will be seen that lever 102 is bifurcated at its other end so as to embrace the hub of cam 104, shown in Fig. 14, which together with gear 55, cam 105, and cam 106, shown in Figs. 15 and 16, is slidable against the restraint of spring 107 as well as rotatable upon a short shaft 108 which is mounted between side frame 48 and a triangular plate 109 attached to side frame 48 by means of three legs 110, 111 and 112. Accordingly, the movement of shifter lever 102 causes narrow-faced gear 55 to slide axially with respect to relatively broad-faced gear 53 with which it remains engaged, and causes the consequent simultaneous disengagement of cam 104 from its follower 113, of cam 105 from its wiper follower 114 which is provided upon a pin 115 fixed in plate 109, and of cam 106 from its wiper follower 116 which is pivotally mounted upon a stud 117 attached to plate 109, particular reference being made to Figs. 7, 9 and 13. Accordingly, during the period in the cycle of their disengagement, the cam followers 113, 114 and 116 are disposed in the spaces provided therefor and shown to the right of their respective cams in Fig. 13. The cam disengagement, however, takes place during the interval in which moving lever 65 engages T-shaped cam member 66, effecting the consequent movement of lever 65, pin 70, cam shifter lever 102 and the axial movement of cams 104, 105 and 106, and gear 55, against the restraint of spring 107 which causes the return of the cam and gear unit subsequent to but not at the moment when lever 65 becomes disengaged from T-shaped member 66 to effect the engagement of cams 104, 105 and 106 with their followers 113, 114 and 116, respectively. The delay in the engagement thereof being due to the fact that the cam followers, upon being disengaged from the cam faces, drop behind the cam discs, which thereafter, because of greater radius, prevent the axial return movement of the cam and gear unit until the smallest radius of cam 105 permits the return of its follower 114, and accordingly the reengagement of all of the cams under the pressure of spring 107, the cams being rotated by gears 53 and 55.

Approximately at the moment that lever 65 engages T-shaped member 66, causing the disengagement of the cams as described above, a pin 75

118, upon hook latch 72, which has been moving arm 73 by virtue of its being hooked around pin 71 upon lever 63 which is being driven by gear 60, engages spring-pressed pawl 119, pivoted upon lever 67, which thereupon pries pin 118 and consequently latch 72 radially outwardly to effect the unhooking of latch 72 from pin 71. This results in the temporary arresting of paper carrying arms 73 and 75 at approximately the moment that the cams are disengaged, and accordingly follower 116 is released from its cam 106 and is moved inwardly, i. e. toward the cam axis 108, which causes the movement of link 120, attached to the free end of follower 116, the other end of the link being attached to one of levers 121 which are mounted upon a tubular shaft 122, the ends of which are journaled in the side frames 48 and 49. Two coil springs 123 are attached by one end to the side frames 48 and 49, and by the other end to levers 121, so that they exert a tensional force upon levers 121 and link 120 and normally effect the constant pressure of follower 116 upon cam 106, as well as causing the downward movement thereof upon its being released from cam 106. The other ends of levers 121 are attached, by means of links 124, to a knife-carrying frame 125 which is freely slidable in angular guides 126 formed in side frames 48 and 49, as shown in Figs. 7 and 17. The triangular-shaped knives 127 are parallelly arranged and fixed to frame 125 by means of screws 128 so as to coat with anvil 129 to effect a shearing action to sever the web of sheet material normally disposed between knives 127 and anvil 129 as springs 123 draw knife frame 125 upon guides 126 when cam 106 is shifted by the tripping of lever 65. It is now apparent that when the paper is severed from the web, as above described, the paper carrying arms 73 and 75 are temporarily stationary, after which they resume their travel. The paper carrying arms 73 and 75, having passed the point at which lever 65 engages T-shaped member 66, proceed as gear 60 continues to turn in a counter-clockwise direction, and accordingly to move oscillatory crank lever 57 which effects the movement of arm driving lever 63. The unhooking of latch 72 and pin 71 on arm driving lever 63 caused a temporary arrest in the travel of the paper carrying arms 73 and 75, which halt was for the purpose of severing the paper and was of a duration of time equivalent to the time required for pin 71 upon lever 63, which is continually moving, to catch up with a shoulder 71^a in latch 72 thereby re-establishing the driving connection from lever 63 through latch 62 to the arm 73 which is thereupon driven forward as before.

As the paper carrying arms proceed through their forward and upward arc, but before their extreme forward position is reached, pin 130, upon rotating gear 53 engages lever 131, which is pivotally mounted on a pin disposed on the side frame 48 and stopped against downward movement by a fixed stud 132, and moves lever 131 upwardly to move crank 133 which is pivotally mounted on a boss 134 on side frame 48. Such movement, resisted by coil spring 135, is transmitted by pull rod 136 to lever 137 and causes the rotation of rod 138, the ends of which are journaled in the side frames 48 and 49. The rotation of rod 138 causes contact roller 139 to actuate lever 140 about rod 141 as an axis, which is suspended at either end from rod 142 by means of a pair of levers 143. The angular movement of lever 140 raises ejector roll 144 away from plate 145 for an interval of time sufficient to permit the

paper carrying arms 73 and 75 to insert the forward projecting edge of the sheet of paper or other material they carry between roll 144 and plate 145, which interval is equal to the time required for pin 130 to travel over the curved dwell surface of lever 131, after the release of which, spring 135 causes roll 144 to fall and hold the sheet of paper securely in position upon plate 145.

Having released lever 131, pin 130 on gear 53 next engages lever 146 which imparts an upward impulse to lever 147 both of which are pivotally mounted upon boss 134, lever 147 having a laterally projecting lug 148. At the instant that lever 147 received its upward impulse, pin 81^a fixed upon slidable member 81, has reached a point in its travel with arm 73, which is in a juxtaposition to lug 148, the aforementioned upward impulse of which thereupon trips pin 81^a and causes attached member 81 to move radially outwardly. The radial outward movement of slidable member 81, and, through crank levers 85 and connecting rod 76, the consequent simultaneous outward radial movement of slidable member 82, results in the opening of paper gripping fingers 79 and 83 to release the paper, the forward projecting edge of which is already gripped between roll 144 and plate 145. This outward movement of member 82 causes spring-pressed latch 81 to again engage the notch in member 82, whereupon it is retained in its outward position and the paper gripping fingers 79 and 83 remain open, as is illustrated in Fig. 8.

The extreme forward and upward limit of the movement of the paper carrying arms 73 and 75 is governed by the arc through which crank lever 57 is thrown by the movement of roller 56 in its rectilinear groove. Owing to the relative positions of arc 59 and the pivot point 58 of lever 57 with respect to the axis 54 of gear 53 and its roller 56, it will be seen that the movement imparted to crank lever 57 during the upward movement of the paper carrying arms 73 and 75 is relatively slow, because of the large angle through which roller 56 moves, and interrupted because of the pause provided for severing the sheet of paper or other material from the web. The slow forward movement of the paper carrying arms is provided to permit the proper and precise action of the paper carrying, severing and measuring mechanisms, so that the paper carrying cycle is effective and accurate without damage to the sheet material which might result if greater speed were used. However, upon the reversal of the direction of the angular movement of crank lever 57, which is occasioned by the upward movement of roller 56 as it passes to the side of the vertical center line of gear 53, it will be seen that the relatively small angle through which roller 56 moves to again reverse the direction of the movement of crank 57, causes a very rapid return movement of crank 57 and the consequent uninterrupted quick return movement of the paper carrying arms 73 and 75 to the original position shown most clearly in Figs. 7 and 8, since accordingly as crank 57 reverses in movement, the rotation of pinion 60 is also reversed. The speed ratio of the quick return movement of the arms 73 and 75 to their slow forward paper feeding movement is approximately four to one. As pinion 60 begins to rotate in the reverse direction, lever 63 moves with it and away from arm 73, since it has been previously unlatched therefrom, until the angle between lever 63 and arm 75

73 is sufficient to permit the re-engagement of spring-pressed latch 72 with pin 71, whereupon, after the resultant pause, lever 63 and arm 73 are again connected by latch 72, and lever 63

5 pulls arm 73 and consequently arm 75, with it through an uninterrupted return orbit into the original position shown in Figs. 1, 3, 7 and 8, and the paper carrying cycle recommences upon the timed reversal of oscillating crank 51.

10 The sheet material supply consists of two or more separate sources which are disposed in the pedestal of the machine, any one of which may be selectively drawn upon at the will of the operator or automatically as desired. By referring particularly to Fig. 3, it will be seen that there are two sheet material supply rolls, 150 and 151 which are primarily mounted upon brackets 152 and 153, respectively, a pair of each of which are secured to and project from the rear of the standards 1

15 and 2 constituting the pedestal of the machine. The ends of the axles 154 and 155 of the rolls 150 and 151 are respectively mounted upon two pairs of freely rotatable bearing rollers 156 and 157 respectively attached to the brackets 152 and

20 153. Each of the supply roll axles 154 and 155 is provided with disc collars 158 and 159, respectively, against which arcuate brake shoes 160 and 161 respectively bear, being pivoted in brackets 152 and 153, whereby the rolls 150 and

25 151 are prevented from unrolling or overrunning as the sheet material is rapidly drawn therefrom by the machine, the pressure of brake shoes 160 and 161 being governed by the weight and angle of respective levers 162 and 163. The sheet material webs 150^a and 151^a pass respectively from supply rolls 150 and 151 under tensioning rolls 164 and 165, which are mounted upon levers 166 and 167 pivotally secured upon shafts 168 and 169, respectively, which are fixed between standards 1 and 2 of the machine pedestal. Levers 166 and 167 are provided with collinear extensions 170 and 171, upon which are adjustably mounted the respective counterweights 172 and 173, by which the tension of the webs of sheet material may be regulated, since the pressure of rolls 164 and 165 upon the web is thereby variable. Accordingly, the rolls 164 and 165 are continually hunting to maintain the proper tension of the webs of sheet material passing under them. If, however, the material tends to draw off of rolls 150 and 151 too

40 slowly or drags, the consequent tightening of the web raises rolls 164 and 165, whereupon the cam action of projections 174 and 175 at the bases of levers 162 and 163 and disposed so as to be coplanar with the respective ends of levers 162 and 163, raises said levers away from shafts 168 and 169, which accordingly releases brake shoes 160 and 161 from discs 158 and 159 respectively. Thereupon the rolls 150 and 151 are free for readier revolution and the webs may consequently be drawn off more easily until the slack in the web is sufficient to allow rolls 164 and 165 to assume their normal position as shown in Fig. 3, and the brakes 160 and 161 are again automatically applied to the rolls to retard any overrunning tendency which may have resulted. It is to be understood that the plurality of sheet material supply mechanisms work individually and that ordinarily only one of them is in use at a time.

45 50 55 60 65 70

70 The webs of sheet material, such as 150^a and 151^a shown in Fig. 3, are passed over guide tubes 176 and 177, respectively, which are mounted between side frames 48 and 49 as illustrated more clearly in Figs. 3, 7 and 8. The two webs of sheet

material are then threaded between the paper guide aprons 178 and 179, which are respectively shown in Figs. 20 and 19, and certain spaced relatively narrow guide strips 187 and 190, shown in Figs. 18, 21 and 22, until the forward edges of the webs of sheet material are even with the top edges of aprons 178 and 179. Referring to Figs. 7 and 18, it will be seen that the aprons 178 and 179 project upwardly in a curve coincident with the arc described by the paper gripping fingers 79 and 83 which are embraced by the inner lateral edge of front apron 178, which is shown so registered in Fig. 7, and the lateral edge of rear apron 179 when it is in position to register with fingers 79 and 83. The aprons 178 and 179 are fastened by their lower edges to a pair of like cross bars 180 and 181, respectively, of the paper switching frame 182, which is suspended from two pairs of parallel motion links 183 and 184, respectively, from tubular shafts 185 and 186 which are journaled at the bottom of side frames 48 and 49, as is most clearly shown in Figs. 7, 8 and 17. Coacting with aprons 178 and 179 are the two pairs of guide strips 187 shown in Fig. 21, a pair of each of which are disposed so as to be even with the inner lateral edges of front apron 178 and with the lateral edges of the apron 179, as well as parallel to the rear surfaces of each so as to form a narrow space through which the web of sheet material may freely pass without wrinkling. The guides 187 for front apron 178 are mounted by their lower ends upon bosses formed on cross bar 181 of frame 182, whereas the guides 187 for rear apron 179 are likewise fastened by their lower ends to brackets 188 which are fixed to another cross-bar 189 of frame 182. A similar guide 190, shown in Fig. 22, is mounted at the centers of and so as to co-act with aprons 178 and 179, the center guide 190 for front apron 178 being mounted at its lower end upon a boss on cross-bar 181 of frame 182, and the center guide 190 of rear apron 179 being mounted at its lower end upon a boss on cross-bar 189 of frame 182. Journaled in lugs formed on brackets 188 on cross-bar 189 and in like lugs formed on cross-bar 181 are articulated shafts 191, which are so formed, as shown in Fig. 18, as to be self-aligning and flexible within limits to compensate for the unavoidable variations in the web feed and its various guiding systems. Levers 192 are mounted at each end of shafts 191 and carry the ratcheted rollers 193 provided with a series of friction rings 194 for the purpose of smoothing and constraining the web to the aprons 178 and 179 and for restraining the web against being drawn backward by virtue of their ratchets 195 shown in Figs. 17 and 18. Articulated shafts 191 are each provided with a pair of rigid lever brackets 196 near their ends which co-act with similar rigid extensions in brackets 188 and on cross-bar 181, between which and aforesaid lever brackets 196 are disposed coil springs 197, which effect the constant pressure of friction rings 194 of rollers 193 against the web of sheet material, which is disposed upon the under surfaces of aprons 178 and 179, as may be readily seen by referring to Figs. 7, 17 and 18.

75 80 85 90 95 100

The sheet material switching system is provided for the purpose of changing the character of the interposed layers of sheet material being wound upon the winding spindle, either before the winding operation has begun, or during the winding operation, when, for instance, it is desired for insulation purposes to have a different type of wire layer separation between the first and last few layers of wire, such as heavy paper, 75

oiled linen, silk, or the like. The sheet material switching mechanism may be selectively operated manually or automatically, as desired, and the new material is automatically interposed 5 between the elected wire layers without interruption of the winding process, since the switching can only be done at the proper instant, due to the protective timed mechanism which is to be hereinafter described. As above disclosed, 10 switching frame 182 is suspended by parallel motion links 183 and 184 from shafts 185 and 186, respectively, which are journalled in the side frames 48 and 49 so as to allow the free swing of frame 182 when actuated. Referring particularly to Figs. 7 and 14, it will be seen that a bell-crank lever handle 198 is rigidly fastened to shaft 185, so that any motion of handle 198 causes motion of frame 182, whereas the locking of handle 198 likewise locks frame 182 against 15 any motion. By additional reference to Fig. 9, it will be seen that handle 198 is provided with a circular hole in its elbow, which is adapted to normally register with a slightly elliptical hole near the bottom of side frame 48 and through 20 which a pin 199 is normally inserted, which pin is fitted to and slidable in the hole in handle 198 and pivotally mounted at its end to one end of lever 200, which is fulcrumed between a pair of ears 201 integral with handle 198 and is forced 25 away from handle 198 by a coil spring 202. Accordingly, upon the withdrawal of pin 199 from its engagement with the registering hole in side frame 48 by manually squeezing lever 200 against handle 198 and then pulling upwardly upon 30 handle 198, switching frame 182 may be swung upwardly upon parallel motion links 183 and 184 pivoted on shafts 185 and 186, respectively, until rear apron 179 and its coacting sheet material guiding system register with anvil 129, where- 35 upon paper carrying fingers 79 and 83, upon their return downward movement will embrace the web of sheet material 151^a, which is served by supply roll 151, instead of web 150^a, which had been served by supply roll 150 due to the former 40 position of the switching mechanism, as is best illustrated in Figs. 3 and 7. However, owing to the fact that the original web 150^a of sheet material is being unrolled from roll 150, as shown in Fig. 3, and is moving over front apron 178 and anvil 129, by virtue of being drawn upwardly by the paper carrying arms 73 and 75, it would be impractical to attempt to switch to another 45 source of sheet material such as web 151^a upon apron 179, because of the obvious damage to the webs and to the feeding thereof, if such switching is intended to be done during the winding process. Accordingly, the switching mechanism is locked during the movement of the web of sheet material, but is automatically unlocked 50 when the web stops moving, which occurs only after the knife mechanism has severed the feeding sheet from the web, whereupon both webs 150^a and 151^a are stationary upon their respective aprons 178 and 179.

55 Referring now to Figs. 7, 9 and 13, and particularly to Fig. 14, it is apparent that cam 104 controls the locking and unlocking of the switching mechanism, whereby the withdrawal of pin 199 is either prevented or permitted according 60 to the position of cam 104. Follower roller 113 of cam 104 is mounted upon the end of a bell crank 203, fulcrumed upon a pin 204, fixed in side frame 48, and the other end of bell crank 203, is pivotally attached to the end of a slide member 205 which is slidable in a guide provided 65 therefor in side frame 48, and which is provided at its other end with a hole which is adapted to normally register with the respective coacting holes in side frame 48 and handle 198 to permit the insertion of locking pin 199, pin 199 being 5 notched, as shown in Fig. 14, so that when the edge of the hole in slide 205 engages it, it cannot be withdrawn until the movement of slide 205 takes place, which movement is controlled by cam 104. Accordingly, when cam 104 is shifted 10 along with cams 105 and 106 and gear 55, as heretofore explained and which occasions the severing of the web, follower 113, being released from cam 104, causes the slide 205 to move to disengage the notch in pin 199 so that it may be 15 withdrawn by pressing lever 200 against handle 198, and, by pulling up on handle 198 the material is changed, and pin 199 subsequently registers with and slides into holes 206 in the center of slide 205 and in side frame 48 when handle 20 198 is released, whereby the switching mechanism is locked in its other extreme position. A coil spring 207, attached by one end to side frame 48 and by the other end to bell crank 203, tends to maintain the constant pressure of follower 25 113 on cam 104, causes it to drop behind cam 104 when the cam is shifted, and draws slide downwardly to release pin 199 when cam follower 113 is moved inwardly. Referring to Fig. 7 it is evident that the rotation of cam 104, during the time of travel of the paper carrying arms 73 and 75 up to the point where they pause for the severing of the web, maintains the switching mechanism locked due to the shape of the cam edge of cam 104 and its resultant dwell action, 30 whereby there is no relative motion of its follower 113, but that, after the shifting of cam 104 and until its follower 113 re-engages it before the gripping fingers 79 and 83 again grip the lateral edges of the web, the pin 199 is released and may be withdrawn at will. 35

As the paper carrying arms 73 and 75 begin their forward and upward journey from their extreme lowest position shown in Figs. 3, 7, and 8, their gripping fingers 79 and 83 embrace but do 40 not grip the lateral edges of the registering one of webs 150^a or 151^a, the leading edges of which are even with the top edges of aprons 178 and 179, respectively. Assuming that the sheet material switching mechanism is arranged as illustrated in the drawings, i. e., so that the fingers 79 and 83 embrace the lateral edges of web 150^a, which is disposed upon apron 178, the motion 45 of paper-carrying arms 73 and 75 is accompanied by a simultaneous rotation of cam 105, which, owing to the shape of cam edge, causes the lifting of its wiper follower 114, which pivots about pin 115, pulls link 208 forwardly to turn double-armed lever 209 about rod 210 fixed in side frames 48 and 49, which effects the lifting of 50 gripper roller 211 away from anvil 129. Roller 211 is provided with a series of spaced friction rings 212, and at one end with a ratchet 213 which permits it to turn in one direction only, i. e., when the web is advancing beneath it, and prevents 55 the web from being drawn backwardly. The other end of shaft 210 is provided with a single lever 214 for supporting the other end of roller 211 and another lever 215 to which is attached a coil spring 216, as shown in Fig. 8, which tends 60 to maintain gripper roller 211 constantly in engagement with anvil 129, maintains a constant pressure of follower 114 upon the cam surface of cam 105, and also to effect the rapid dropping-off movement of follower 114 from cam 105 as 65 70 75

the latter is shifted along with cams 104 and 106 and gear 55, as heretofore explained. Accordingly, when gripping fingers 79 and 83 grip the lateral edges of the web at a point below the 5 top edge of apron 178 to allow for a forward projection of the leading edge of the web, roller 211 has already been raised away from anvil 129 to allow for the ready insertion of that leading edge 10 of the web, and remains raised until cam 105 is shifted in the manner above described, whereupon 15 spring 216 effects the quick return of roll 211 to grip the web against anvil 129 during the pause in the travel of arms 73 and 75, and when knife 127 moves to sever the sheet from the web, where- 20 by roll 211 assists in the severing action by gripping the web securely to the anvil 129.

The web of sheet material, after being gripped by fingers 79 and 83, is drawn by arms 73 and 75 over anvil 129 and on to a flexible support or platen 217 which is preferably of the same curvature as the arc described by the paper carrying arms 73 and 75. Both anvil 129 and platen 217 are mounted upon a pair of like spiders 218 having an angle-shaped cross-section, the upper ends 25 of which are secured to a cross-bar 219, which is fastened to the front face 220 joining the side frames 48 and 49, as shown in Figs. 7 and 23, and the lower ends of which are secured to a cross-bar 221, the ends of which are mounted upon lugs 30 222 on the lower part of side frames 48 and 49. A pair of tie-rods 223 and 224 are disposed between the spiders 218 in order to stiffen their structure. The sheet material support or platen 217 is mounted by and along its top edge to 35 the top of cross-bar 219. Ejector plate 145 is mounted upon the top edge of the front face 220 joining side frames 48 and 49, so that it may be pivotally adjustable about a stud 225 mounted in the center of top edge of face 220, as shown in 40 Fig. 23, in order that its surface may be readily maintained in alignment with platen 217 and, tangent to the winding spindle as shown in Fig. 7. A bracket 226 is provided in each of the spiders 218 upon which is mounted a cross-bar 227 45 to which the lower edge of platen 217 is fastened, and to which anvil 129 is also fastened, being given the proper rake by means of a pair of interposed shims 228. Thus platen 217, being of flexible material, is drawn over spiders 218 and partakes of the curvature thereof, which 50 coincides with the arc described by the gripping fingers 79 and 83 of the paper carrying arms 73 and 75.

Substantially concentric with platen 217 is a 55 shield 229, the lower edge of which is fastened to cross-rod 210, and the upper lateral edges of which are adjustably suspended from two brackets 230, which are mounted upon the top flanges of side frames 48 and 49, each of brackets 230 60 supporting a screw rod 231, the lower end of which is fixed to the outer surface of shield 229, and adjustable against the pressure of spring 232 by means of a wing-nut 233, whereby the radial space between platen 217 and shield 229 is made 65 variable. The radial space between platen 217 and shield 229 is preferably adjusted to taper slightly from bottom to top for the purpose of confining the sheet as it approaches the winding spindle, which effect is assisted by the light 70 constraint of several smoothing threads 234 which are stretched between the lower and upper edges of shield 229 so that they lie substantially along the entire surface of platen 217 and parallel to the path of the moving sheet. The 75 threads 234 are taut enough to exert sufficient

pressure on the sheet to smooth out the transverse ripples therein, which result from its being tightly rolled on the supply roll, but are not taut enough to retard the progress of the sheet. Accordingly the sheet is constrained and smoothed to the curved platen 217 during the entire course of its travel, so that when it is applied to the winding spindle 235 it is a perfectly flat sheet. 5

The severed sheet, having been deposited under and subsequently gripped by ejector roll 144 in 10 the manner heretofore described, is then in readiness for application to the continuously rotating winding stick 235. Ejector roll 144 is provided at one end with a ratchet 236 shown in Fig. 2, which operates to prevent rotation of the roll 144 15 as it moves toward the spindle 235 but allows rotation thereof when the roll 144 is retracted. Accordingly when roll 144 advances over the surface of plate 145, its non-rotating friction 20 surface acts as a pusher which causes the sheet disposed beneath it to be ejected so as to be applied tangentially to the winding spindle. By referring to Figs. 7 and 8, it will be seen that the ejector roll 144 is actuated by a linkage comprising levers 140 and 237 which carry ejector 25 roll 144 and are pivoted upon shaft 141, which in turn is suspended from shaft 142 by means of levers 143 and 238, the latter being provided with an upward extension to which is attached 30 a pull rod 239. As illustrated in Fig. 8a, pull rod 239 is pivoted to one end of a double crank 240, which is fulcrumed in a bracket 241 attached to the under side of a crossbar 242 joining the upper portions of side frames 48 and 49. To the other 35 end of double crank 240 is attached a lever 243 which carries a cam roller 244 and at the same point is attached to one end of a link 245 the other end of which is pivotally mounted upon a pillow block 246 attached to the top of bed plate 3, and is maintained in contact with double-nosed 40 cam 247 by means of a coil spring 248 fixed by one end to bed plate 3. Double-nosed cam 247 acts to effect the periodic projection of the ejector mechanism into the position shown in phantom 45 in Figs. 8 and 8a for the purpose of ejecting the sheet to be applied to winding stick 235 at the proper instant, cam 247 being fixed to and actuated by the rotation of cam shaft 249, the actuation and further purpose of which is to be described hereinafter. 50

In order to maintain the proper relations between the sheet material feeding and driving cycles, a synchronizing mechanism is provided whereby the sheet material feeding mechanism 55 is maintained in step with the driving mechanism, so that the sheet is applied to the winding spindle at the proper instant. Accordingly, a double nosed cam 250 is mounted upon shaft 251 normally connected, as shown in Figs. 2 and 4, by 60 a sleeve coupling to cam shaft 249 and rotating therewith, and which cam is engaged by a follower 252 at one end of a bellcrank 253, which is pivoted upon a bracket 254 mounted upon the rear surface of bed plate 3, as shown in Figs. 2 and 4. A push rod 255 is attached to the other end of bell crank 253, and accordingly transmits the oscillatory movement effected by cam 250 to a stop lever 256, the other end of which is pivoted 65 upon the inner face of side frame 48 as is illustrated in Fig. 7. As gear 53 rotates, pin 130 attached thereto periodically engages the stop projection of lever 256, which occasions the stoppage of gear 53 and consequently the entire sheet 70 75

material feeding mechanism since it is actuated by gear 53, until cam 250 releases stop lever 256 at the instant when the driving mechanism actuating shaft 251 catches up with the sheet feeding mechanism and the required synchronous relation between them is attained. Consequently, in view of the synchronizing mechanism, gear 53 is given a periodic motion which is imparted to its driving pinion 41, and its connecting shafts 46, 45, and 39, which latter shaft is attached to the output side of slip coupling 38, which accordingly slips during the periods of rest of the aforementioned gears, since the other side of slip coupling 38 is constantly driven by gear 34, which action may be followed by reference to Figs. 2, 5 and 7.

The step-by-step or periodic motion imparted to shaft 39 is transmitted, by a pinion 256' attached thereto, to a gear 257 mounted beneath it and fastened to a short horizontal shaft 258 the other end of which is journaled in a bracket 259 mounted upon bed plate 3, as shown in Figs. 2 and 1. A bevel pinion 260 is pinned to shaft 258 and meshes with a bevel gear 261 attached to the upper end of a vertical shaft 262 passing through bed plate 3, the lower end of which is provided with a worm 263, as shown in Fig. 1. Worm 263 drives a worm wheel 264, which is mounted upon a horizontal shaft 265 journaled at one end, together with shaft 262, in a bracket 266 suspended from the under side of bed plate 3, and at the other end in a bracket 267 attached to the front web of bed plate 3. Shaft 265 is provided with a pinion 268, as shown in Figs. 1 and 3, which meshes with a rack cut into the under surface of a rod 269 which is longitudinally movable upon grooved rollers 270 revolvably attached to brackets suspended from bed plate 3, as seen in Fig. 1. Rod 269 is provided with a rigid depending arm 271, the end of which is provided with a roller 272 which engages a longitudinal slot in an angular bar 273 which is adjustably mounted upon a flat cross beam 274 joining the two side frames 48 and 49, as illustrated in Fig. 1. As viewed in Fig. 1, the right-hand end of slotted bar 273 is normally rigidly clamped in a transverse T-slot in beam 274, whereas the other or left-hand end of slotted bar 273 is mounted upon a nut 275 disposed in another transverse slot in beam 274, the position of which nut is vertically adjustable by means of a screw 276 threaded therethrough and actuated by a thumb-nut 277, as shown in Figs. 1 and 24. Consequently, as rod 269 is moved longitudinally according to the periodic motion imparted to it by shaft 45 through the above described gearing, roller 272 moves horizontally in slotted bar 273, which, by virtue of its angular position, is given a relative motion upwardly, and since it is rigid with beam 274, the entire carriage, comprising side frames 48 and 49 and their attached parts, pivots about shaft 50 which is supported on trunnion brackets 51 and 52 mounted upon bed plate 3, as is shown in Figs. 7 and 8.

The above described motion of the carriage compensates for the increasing diameter of the stick of coils 235 being wound upon the winding spindle, and is the means whereby the surface of ejector plate 145 is maintained tangent to the winding stick of coils, in order that the sheet material may be applied tangentially thereto. Inasmuch as the initial or starting diameter of the core or stick on the winding spindle marks the beginning of the travel of rod 269 and the consequent horizontal movement of roller 73 272 in slotted bar 273 to effect the periodic ele-

vation of the carriage, the starting diameter dimension of the core or stick is set on scale 278 according to pointer 279 by turning thumb-nut 277 to move nut 275 and consequently the left hand end of bar 273. Inasmuch as the amount of periodic elevation required of the carriage in order to maintain the aforesaid conditions of tangency is equal to the sum of the thickness of the wire or other strand material and the thickness of each layer of sheet material, the pitch 10 of bar 273 is set to that dimension as indicated upon the graduated sector 280, which has been calibrated so that the pitch of bar 273 effects the periodic rise of the carriage by an amount equal to the thickness of one layer of strand material plus the thickness of the layer of paper or other material. The left hand end of bar 273 having been set by moving pointer 278 to the starting diameter dimension on scale 278, nut 281 at 15 the right-hand end of bar 273 is loosened and 20 bar 273 is moved angularly until its upper edge coincides with the proper graduation on scale 280, as above described, whereupon nut 281 is again tightened to lock bar 273 in the correct 25 angular position.

Since the travel of rod 269 is proportional to the increasing diameter of the winding spindle, its movement has been calibrated into terms of layers of strand and sheet material, and accordingly a circular scale 282 is provided upon shaft 265 30 which actuates rod 269, said scale 282 being adapted to co-operate with a pointer 283 attached to bracket 267. By means of this arrangement the number of layers which have been wound upon the spindle are counted and may be observed at any instant. A knurled knob 284 is provided at the outer end of shaft 265, whereby, by pulling on knob 284 against coil spring 285 disposed on shaft 265 between the front web of bed plate 3 and a collar 286 fixed on shaft 265, 40 shaft 265 may be moved longitudinally to disconnect it from worm wheel 264 to which it is normally clutched. By referring to Fig. 25, it will be seen that the rear end of shaft 265 is journaled in the hub 287 of worm wheel 264, which hub is in turn journaled in bracket 266 and positioned by collar 288. Worm wheel 264 is provided with one-half of a jaw clutch, whereas the other half 289 thereof is pinned to shaft 265, so that by pulling outwardly on knob 284, shaft 265 50 is de-clutched from worm 264 which continues to rotate, its lowest edge being immersed in a lubricating bath of oil disposed in a trough 290 attached to bracket 266. Accordingly, by de-clutching shaft 265 and turning knob 284, the 55 entire carriage may be raised or lowered by hand, which device is used to bring the carriage back to the initial starting position to begin a new winding, as for example, when a stick of coils has been completed and it is desired to begin a new 60 one.

An automatic machine stopping mechanism is provided which is adapted to stop the mechanism when a required number of layers of complete 65 windings have been wound upon the winding spindle. The stop mechanism operates in conjunction with the layer counting mechanism above described, and consists of a rod 291 which acts as a telescopic extension of rod 269 and is variably positionable relative thereto by means 70 of a tightening collar 292, rod 291 being positioned so as to be aligned with the tip of a trip lever 293 attached to trip handle 18 which is maintained in a relatively fixed position by coil spring 294 as shown in Fig. 2. As heretofore 75

explained the tripping of handle 18 actuates clutching handle 10 to effect the declutching of the machine from the driving means or motor 4. Likewise the outward movement of lever 293 causes the tripping of handle 18. Assuming that twenty layers are to be wound upon the spindle, knob 284 is then withdrawn to declutch shaft 265 from its driving worm wheel 264, and knob 284 rotated from the zero reading of scale 282 10 until graduation twenty coincides with pointer 283, whereupon rod 291 is slid outwardly until its tip engages lever 293 at its extreme outward and declutching position, collar 292 is clamped to fix rod 291 securely in that position to rod 269, and knob 284 is again rotated to return scale 282 to zero reading. Accordingly, rod 291 will engage trip lever 293 to effect the stopping of the machine when the twenty layers have been wound upon the machine, since rod 269 moves with the 20 layer counting mechanism.

As the diameter of the stick of coils upon the winding spindle increases, due to the successive addition of layers of strand and sheet material thereto, the length of the successive sheets must be increased in order to continue to make at least one complete wrapping plus the lap around the stick of coils 235. Accordingly, a paper measuring mechanism is provided which automatically increases the length of the successive sheets as 25 they are severed from the web, in order to compensate for the increasing diameter of the stick of coils on the winding spindle. As heretofore explained, the paper gripping fingers 79 and 83, at the extremities of paper carrying arms 73 and 75, are closed to grip the lateral edges of the web of paper and hold it taut at a point slightly below the top edge of apron 178 with which the leading edge of the web coincides, having been severed at that point by the knives 127 during the preceding paper feeding cycle. The length of paper between the leading edge of the web and the point where the fingers 79 and 83 grip the lateral edges thereof has been termed the forward projection of the paper, and is that which is inserted 40 and deposited under ejector roll 144 at the end of the paper carrying travel of arms 73 and 75, which forward projection is accounted and compensated for by the paper measuring and severing mechanism.

The length of the sheet of material to be applied to the spindle is governed by the position of lever 67 to which is attached the T-shaped wiper block 66, which, by the engagement of lever 65 therewith, accordingly effects the shifting of the 45 cam and gear unit illustrated in Figs. 9 and 13, and, in the manner heretofore explained, causes the severing of the thus measured sheet from the web during the pause in the movement of paper carrying arms 73 and 75. Obviously, the 50 lengths of the successive sheet layers are proportional to the successively increasing diameter of the stick of winding coils, and the necessary increase in length of each sheet, in order to make a complete wrapping, is accordingly proportional 55 to each increase in diameter of the stick. Consequently the angle through which lever 67, which carries the T-shaped tripping member 66, must be moved to compensate for the increasing diameter of the stick is proportional to the angle 60 through which the entire winding carriage must be moved in order to maintain the tangency of ejector plate 144 to stick 235. Accordingly, the movement of the carriage is utilized to measure the successive sheets of paper as they are severed 65 from the web, and the lengths thereof are

progressively increased to take care of the increasing diameter of the winding stick 235.

Mounted upon the front ledge of bed-plate 3 is a bracket 295 which carries rack 296, between which and the carriage there is a relative movement. Accordingly, such relative movement causes the rotation of pinion 297, which meshes with rack 296, and which is journalled on a stud 298 attached to side frame 48, as is most clearly illustrated in Fig. 7. Pinion 297 drives pinion 299, which, together with pinion 300 and cam 301 are integrally mounted upon a stud 302 which is fixed in a block 303 attached to the inner surface of side frame 48, as shown in Figs. 7 and 9. The teeth of pinion 300 are in mesh with those of gear 304 which is staked to lever 67 but which is free to rotate upon the hub of pinion 60. A detent pawl 305 is pivotally mounted upon block 303 and is spring-pressed by means of leaf spring 306 attached to the top edge of block 303 so that the heel 307 of detent 305 bears against the surface of cam 301 and drops into the notch therein whenever cam 301 is turned into the proper position for such engagement. When detent pawl 305 drops, as its heel 307 engages the notch in cam 301, a projecting lug 308, at the extremity of pawl 305, falls between the teeth of gear 304 and accordingly stops the movement thereof and of lever 67, which has been moving in an upward direction through the agency of rack 296, and pinions 297, 299, 300 and 304. Accordingly, lever 67 has assumed a new position whereby the next sheet severed from the web is proportionally longer than its predecessor to compensate for the increased diameter of the spindle. It will be seen that the stopping and moving of lever 67 is governable by the shape of cam 301, which, as illustrated in the drawings, is designed for making one complete wrapping plus a lap around the stick of coils, and may be readily replaced when it is desired to make more than one wrapping of sheet material, by a cam designed particularly for that purpose. It is evident that the movement of lever 305 must be synchronized with the periodic movement of the carriage as heretofore explained, and further that the interruption in the teeth of pinion 300 is arranged relative to meshing gear 304 so that they become disengaged when lug 308 on detent 305 engages the teeth of gear 304 to stop it. Lever 67 is positioned periodically during the paper carrying cycle so that the sheets are cut to successively longer lengths as the stick of coils is built up, and therefore the tripping engagement of lever 65 with member 66 on lever 67 is deferred periodically which consequently defers the action of the severing mechanism.

In order that the forward projection of the web, which is the short length thereof between the leading edge of the web and the places where the gripping fingers grasp its lateral edges, may be maintained constant no matter what the trailing paper length is and consequently irrespective of the elevation of the carriage, a compensating mechanism is provided for that purpose. Accordingly finger-closing latch 93 must be repositioned as the carriage moves, and since latch 93 is fixed to lever 91, the latter must be moved as the carriage moves. The lower end of lever 91 is pivoted to a short crank 309, which is pinned to shaft 310 journalled in bearing brackets 311 and 312 which are mounted upon the inner surface of cross-beam 275, as illustrated in Figs. 8 and 10. To the other end of shaft 310 is pinned link 313, the free end of which is provided with

1 a pin 314 which projects through slot 315 formed in the wall of side frame 49. Link 316 is pivoted upon the outside end of pin 314, and is suspended by pin 317 from bearing bracket 318 fixed to the top surface of bed plate 3, as shown in Figs. 8 and 10. By referring to Fig. 8, it will be seen that an upward movement of the carriage about bar 50, upon which it is trunnioned, causes pin 314 to move downwardly to the right, since the distance between fixed pin 317 and moving shaft 310 is being gradually decreased, and consequently lever 91 is being slowly moved downwardly to the left. Inasmuch as the rate of movement of lever 91 and latch 93 fixed thereto is proportional to the movement of the carriage, the paper gripping fingers 79 and 83 are closed at the same relative position upon the lateral edges of the web with respect to its leading edge, whereby the length of the forward projection of the web is maintained constant irrespective of its increasing severed length or the position of the carriage. Inasmuch as the closing of the paper gripping fingers is effected by the engagement of pawl 90 with latch 93 the forward projection of the web may be varied at will by altering the shape of latch 93. Accordingly, a number of variously shaped, interchangeable latches 93 are provided as part of the equipment of the machine.

2 The winding spindle driving system consists essentially of a gearing and belt-and-pulley mechanism whereby the higher speeds, which are preferable for small diameter fine wire coils, are obtained by a two speed belt-and-pulley combination with silence and comparatively no vibration, whereas for winding larger and heavier coils requiring a relatively large driving power, a two-speed gearing combination may be selectively utilized. The direct spindle drive and each gear combination is belt driven by a cone pulley, preferably a two-step cone pulley. Referring particularly to Figs. 4 and 4a, it will be seen that the inner end of shaft 7 is pinned to a coaxial sleeve 319, which is provided at one end with an integral pinion 320, and at the other end with half of a normally engaged jaw clutch 321, the other half of which is attached to another sleeve 322 having half of a normally disengaged jaw clutch 323 at its other end, the shank of which, by means of keys 324, is fixed to shaft 325, which is similar to and coaxial with shaft 7 and is journaled in sleeve 319 and hanger 326 suspended from the rear edge of bed plate 3. Shaft 325 is located longitudinally by collar 327 at one side of the hub of hanger 326, and at 55 the other side by collar 328, between which and the hub of hanger 326 is disposed a normally free gear 329 to which the other side of normally disengaged jaw clutch 323 is attached. As above described, shaft 325 and two-step cone pulley 330, which is keyed thereto by keys 331, are driven directly at the same rate of speed and in the same direction as shaft 7 and clutch pulley 6 to effect the normal forward drive, the reverse drive being described hereinafter.

65 The head-stock of the machine through which the winding spindle is driven is illustrated in enlarged views of Figs. 26 and 27, and is encased in a housing 332 which is mounted upon bed plate 3 and at its forward edge as shown in Figs. 1, 2, and 3. Driving two-step cone pulley 330 is connected to the detachable two-step cone pulley 333 of the head-stock by means of belt 334 whereby two initial belt speeds are obtainable at will. As shown in Fig. 26, pulley 333 is attached 70 to shaft 335, for the direct drive of the winding

75 spindle, which drive is only variable by the other pulley step when pulley 333 is attached to shaft 335. For the lower spindle speeds, pulley 333 must be transferred to shaft 336, as shown in phantom in Fig. 26, which is done by removing lock nut 337, slipping pulley 333 off of the end of shaft 335 to which it is keyed by keys 338, and unscrewing collar 339 from shaft 335 by means of a spanner. Shafts 335 and 336 are journaled in the casing 332 upon annular ball bearings 340 which are fixed in position by keeper plates 341, each of which is provided with a shaft packing 342 for keeping moisture and dirt out of the gear casing 332. When shaft 335 is being driven directly, as shown in Fig. 26, spur gears 343 and 344 which are keyed thereto idle disengaged, whereas integral worm 345 drives worm wheel 346 pinned to shaft 347, one end of which is journaled in casing 332 and the other end thereof in a bearing bracket 348 mounted on bed plate 3, as shown in Fig. 2. A gear 349 upon shaft 347 drives a gear 350, mounted upon a bracket 351 attached to casing 332, which in turn drives the pinion 352 of odometer 353, which is utilized for the purpose of counting the revolutions of the winding spindle 354 the end of which is screwed into the work end of shaft 335. Accordingly, the higher spindle speeds are obtained by a direct belt and pulley drive without the intervention of gearing, which higher speeds are particularly adaptable for winding smaller diameter coils and when a relatively fine wire is used, since a large amount of power is not ordinarily required therefor.

30 For obtaining the lower spindle speeds and consequently a greater power for the purpose of winding heavier coils, pulley 333 must be transferred to shaft 336, as above described and shown in phantom in Fig. 26. Shaft 336 is provided with a long pinion 355 which is keyed thereto, and which is always in mesh with a pinion 356 integral with a sleeve 357, the other end of which is provided with a larger pinion 358, and which is pinned to a bushing 359 slidably mounted upon a jack shaft 360, which is journaled in casing 332, as shown in Fig. 26. One end of bushing 359 is provided with an annular groove in which are slidably disposed a pair of diametral pins 361 which are riveted to the tines of a bifurcated crank 362 mounted upon a short shaft 363 journaled in cover plate 364 mounted upon the front face of casing 332. A gear shift lever 365 is pinned to the other end of shaft 363, the angular movement of which into its two extreme positions indicated by the legends "Low" and "Int.", causes the respective engagement pinion 356 with gear 343 or pinion 358 with gear 344, since the angular movement of crank 362 causes the axial movement of bushing 359 and the attached sleeve 357 with its integral pinions 356 and 358. Assuming that the low spindle speed is desired, tap screw 366 is removed and replaced in the registered tap after lever 365 has been shifted to the position coinciding with the "Low" legend, which causes the shifting of pinion 356 to mesh with gear 343, whereupon shaft 335 and consequently the winding spindle are driven at the low speed. By shifting lever 365 into its "Int." position, pinion 358 engages gear 344 and the winding spindle is driven at intermediate speed. When lever 365 is in the "direct" position shown in Fig. 26, pinions 356 and 358 are disengaged from their respective gears 343 and 344 and shafts 336 and 360 are stationary. Thus it will 75

be seen that two relatively high speeds are obtained by the direct belt and two-step cone pulley drive when pulley 333 is mounted on shaft 335 and directly drives winding spindle 354, and that four relatively lower speeds are selectively obtainable by the gearing arrangement together with the two steps on the cone pulleys 330 and 333, i. e., two speeds by shifting lever 365 and one pulley speed change for each position of lever 365. Headstock housing 332 contains a bath of oil for the lubrication of the gears.

In order to lay the wire or other strand material evenly and smoothly upon the winding stick so that the consecutive convolutions are adjacent the previous ones, a strand feed guide mechanism is provided which has been heretofore disclosed in aforementioned Patent 798,864. Shaft 347 which is driven by the head-stock gearing in the manner above described, is provided with a bevel gear 367 which meshes with a pair of bevel pinions 368 and 369 mounted freely upon a short shaft 370, which is journaled in a pair of bearing brackets 371 and 372 attached to the top of bed plate 3. Each of bevel pinions 368 and 369 is provided with half of a jaw clutch adapted to co-act with the ends of sleeve 373, which is splined to shaft 370, so that its engagement with either of pinions 368 or 369 causes the shaft 370 to rotate in either one direction or the other, since those pinions are rotating in opposite directions. Accordingly, the shifting of sleeve 373 from its engagement with pinion 368, as shown in Fig. 2, to engage pinion 369, reverses the direction of rotation of shaft 370. The periodic shifting of sleeve 373 is effected by lever 374, which is fulcrumed at 375 upon bed plate 3, and the other end of which is actuated angularly by cam 376 which is resiliently fixed to cam shaft 249, being disposed between two coil springs 377 mounted between collars 378, as illustrated in Fig. 4a. Referring to Figs. 4 and 4a, it will be evident that the cam shaft 249 derives its rotation indirectly from pinion 379 pinned to rotating sleeve 322, and which is in train with gears 380 and 381 which are suspended from the under side of bed plate 3, gear 381 in turn driving pinion 382 and consequently countershaft 383 which is journaled in brackets 384 and 385 mounted on top of bed plate 3.

The end of shaft 383 is provided with a pinion 386 which meshes with gear 387 integral with the driving element of cone friction clutch 388 (similar to the disclosure of the said prior Patent No. 798,864) the other member of which is coupled at regular intervals thereto, the driving element being splined to shaft 251 as hereinafter stated, said shaft being attached to the end of shaft 249 by the coupling, supra and drives the latter, which shafts are journaled in brackets 389 and 390 mounted on top of bed plate 3.

The rotation of shaft 370 is communicated, by means of spur gears 391 and 392, to shaft 50 which is journaled in bracket 393, and about which the machine carriage pivots, being trunnioned in brackets 51 and 52 mounted on top of bed plate 3, as illustrated particularly in Figs. 7, 8 and 17. Along one end of shaft 50 a lead screw thread 394 is cut and carries a travelling nut 395 upon which is pivoted an upwardly inclined rod 396, the function of which will be explained hereinafter. The nut 395 also carries a projecting pin 397, and moves back and forth along screw 394 as shaft 50 is rotated alternately backwardly and forwardly, due to the periodic move-

ment of lever 374 effected by cam 376. Arranged parallel to the threaded shaft 394 is a bar 398, carrying a rod 399, having a right-hand thread at one end and a left-hand thread at the other end, upon which run nuts 400 and 401, respectively, the rod being normally free to turn upon its bearings by hand manipulation of pinion 402 in order to adjust the distance between the two nuts 400 and 401. In order to prevent the nuts 400 and 401 from rotating with rod 399, they are flattened on one side and bear against the side of bar 398. The pin 397, carried by nut 395, plays back and forth between the two nuts 400 and 401 and strikes one or the other of them at each end of its travel. The bar 398 is mounted to move slightly in the direction of its length by being pivoted on parallel links 403 and 404, which in turn are pivoted on top of bed plate 3. This motion is imparted to the bar 398 by the pin 397 when it strikes one of the nuts 400 and 401. The link 403 carries a double-armed lever 405, extending in opposite direction from the pivot, each end thereof bearing against an adjustment screw in the end of bell crank lever 406, pivoted at 407, and whose other arm engages the sliding and splined portion of cone friction clutch 388 on shaft 251, as is clearly shown in Figs. 2 and 4. From this construction it will be seen that whenever the bar 398 is moved by pin 397 striking either of nuts 400 and 401, the lever 406 is thrown and in the manner disclosed in the said Patent No. 798,864, the splined portion of clutch 388 is caused to engage with continuously rotating portion and the power is applied to the driven portion and shaft 249, which is consequently rotated from shaft 251. Spring 408 tends to restore lever 406 to the de-clutching position. On the rear face of bar 398 are two lugs 409, having horizontal surfaces in the same plane with each other and spaced apart a distance substantially equal to their width. Immediately above the open space between the lugs is a third lug 410, wedge-shaped on the upper surface and with its under surface flat and slightly above the plane of the upper surfaces of the other two lugs 409. Shaft 251 is held stationary by the fact that the extremity of one of the wings 411 thereon is confined between the flat faces of lugs 409 and 410. When bar 398 is moved bodily to the right or left by the engagement of travelling pin 397 with pins 401 or 400, respectively, the lug 409, upon which the extremity of one of the wings 411 is resting, passes to one side, permitting the wing to pass through the space between the two lugs 409. At the same instant lever 406 is moved to throw clutch 388 into engagement, and shaft 251 is accordingly rotated until the extremity of the other one of wings 411 drops upon the upper surface of the other one of lugs 409, and the further rotation of shaft 251 is prevented, clutch 388 being simultaneously disengaged but slipping slightly if it is not released at the proper instant.

The extremities of the two wings 411 are offset axially with respect to each other so that one of them will always engage one of lugs 409, while the other will engage the other lug. This half-rotation of shaft 251 reverses the direction of rotation of shaft 50 by the action of cam 376 on shaft 249 and hence through lever 374 and clutch sleeve 373, so that at the moment when it occurs the direction of movement of nut 395 is reversed and bar 398 is returned to its normal mid-position, illustrated in Fig. 2, by the spring 75

408. This carries lug 410 partially over the edge of the extremity of wing 411 and prevents any possible movement of shaft 251 in either direction until bar 398 is again shifted. Lug 410, by virtue of its wedge shape, furthermore serves to direct the extremity of the wing 411 equally upon either of the lugs 409, so that it will be properly positioned, notwithstanding any loose motion of the parts. At the moment of the reversal of the direction of movement of nut 395, cam 412 mounted upon cam shaft 249 between coil springs 413 and collars 414, by means of lever 415 pivoted on bed plate 3, imparts an additional and quicker motion to nut 395 and to the entire shaft 50 in fact, which more quickly relieves bar 398, allowing it to be righted promptly. This bodily movement of shaft 50 and nut 395 is also for another and more important purpose, which will appear later on. In order to thus bodily shift shaft 50, it is necessary that there should be some longitudinal play between it and its major bearings 393 and 416, and such play is provided by the knurled nut 417 screwed on the extremity of shaft 50, and against which the hub of hand-wheel 418 abuts. Any excessive play is absorbed by springs 413 arranged upon each side of cam 412.

The back-and-forth movements of travelling nut 395 are communicated to rod 396 pivoted thereto, the intermediate portion of which passes through a sleeve 419, which is pivoted by a removable pin 420 to a small slide 421, adapted to be adjusted by means of thumb screw 422 along a block fixed to the outside of the upper portion of side frame 48. The forward end of rod 396 is provided with another pivot sleeve 423 which is pivoted to one end of guide-bar 424 which is slidably mounted on the elevated projections of side frames 48 and 49 so that the alternately reversing angular movement of bar 396 effects the reciprocation of bar 424. Guide bar 424 carries a plurality of adjustably spaceable hubs 425, each of which is provided with an upward projection 426 and a downward projection 427, the extremities of which are provided with small grooved guide rollers 428 and 429, respectively, as illustrated in Figs. 1, 2, 3, 7 and 8. These rollers serve as guides for the wires or strands leading to the winding stick 235, and as many sets of them are in use at a given time as there are coils being simultaneously wound upon the winding spindle. The reciprocating motion of bar 424 is comparatively slow and serves to lead the wires along the winding stick to form the layers. The aforementioned additional bodily movement of shaft 50 effected by cam 412 at the moment of its reversal is imparted to guide rod 424, which carries the strand guides 428 and 429, and serves to incline the lead of the winding strands in the direction toward which the new layer is being built up in order to prevent crowding of the turns caused by the winding of more than one turn on top of the last turn of the finished layer, which would result unless such a momentary increase in lead is provided. The adjustment of slide 421 by means of thumb-screw 422 permits of a slight change in the length of the layers, the major layer length adjustment, however, being performed by adjusting the spacing of nuts 400 and 401 upon threaded rod 399 by manually turning pinion 402 in the proper direction to increase or decrease the spacing of nuts 400 and 401. The hand-wheel 418 on shaft 50 enables the operator to shift bar 424 by hand slightly whenever necessary in correcting any imperfections in

winding. By removing pin 420 and releasing rod 396, a greater movement of bar 424 may be effected.

For the purpose of making bobbin-shaped, pyramid or bank-wound coils, instead of the customary right cylindrical coils, an auxiliary mechanism is provided which may be selectively coupled by the operator either at the beginning of or during the winding operation. This mechanism may be coupled to pinion 402 to drive it in a clock-wise direction, whereby nuts 400 and 401 are gradually brought together so that the travel of pin 397 is decreased and consequently the successive layers of wire are decreased in length. The means for doing this is shown in Fig. 2 and comprises a pinion 430 in mesh with pinion 402, the shaft of which is slidably mounted in a bracket 431 attached to bed plate 3, so that by moving handle 432, pinion 430 may be either engaged with or disengaged from pinion 402 either during or before the winding operation. Pinion 430 is provided with an integral bevel pinion 433 which is in mesh with bevel pinion 434 when spur pinions 402 and 430 are in mesh. Bevel pinion 434 is attached to the end of shaft 435 which is journaled in brackets 416, 28 and 29 and carries a spur gear 436 at its other end, which, through gears 437, 438 and 439, is driven by periodically rotating layer-countershaft 265. Accordingly, nuts 400 and 401 are periodically moved together during each winding cycle, whereby the successive layers of wire are decreased in length whenever pinions 402 and 430 are in mesh. The amount of layer length decrease is obviously variable by varying the speed of rotation of shaft 435.

The tail-stock of the machine, which is illustrated in Figs. 28, 29, 30 and 31, is mounted upon bed plate 3 at its front edge, which position relative to the remainder of the machine is shown in Figs. 1, 2 and 3. The tail-stock is aligned with the head stock and carries the other end of winding spindle 354, which is mounted either as shown in Fig. 29 or as shown in Fig. 30. As shown in Fig. 29, spindle 354 is provided with an integral axial stud 440 which is inserted into the ball bearing 441 provided therefor, and which is mounted in a bifurcation in arm 442 pinned to shaft 443, which is slidably journaled in bracket 444 attached to bed plate 3. Arm 442 may be moved laterally by pulling upon knob 445 attached to the end of shaft 443, which movement is resisted by coil spring 446, which tends to keep arm 442 in the operative position illustrated in Fig. 28. Arm 442 is provided with an arcuate stop member 447, the end of which is fitted with a stud 448, which is normally disposed in an opening provided therefor in a bracket 449 mounted on bed plate 3, for the purpose of positioning arm 442 so that bearing 441 is in alignment with the coaxing drive shaft 335 in the head-stock during operation. Spring 446 normally maintains the engagement of stud 448 with the opening in bracket 449, but, by pulling on knob 445, stud 448 is disengaged from bracket 449 and bearing 441 from spindle 354 so that arm 442 may be thrown backward out of the way, and spindle may be withdrawn longitudinally as well as laterally, after detaching it from the head-stock, if desired. As arm 442 is thrown backward, stop member 447 passes through an aperture in the top of bed plate 3 adjacent bracket 449. In an alternate type of tail-stock spindle mounting, spindle 354 revolves with a pointed pin 450 disposed in bearing 441, the other end of

which abuts a stud 451 screwed into the end of bearing 441. Obviously other well-known tailstock spindle supporting and centering means may be utilized as desired.

- 5 The strand material supply and tensioning mechanism and its position relative to the rest of the machine is illustrated in Figs. 1, 3 and 3a, and particularly in the enlarged views of Figs. 32, 33, 34 and 35. The entire wire supply and 10 tensioning mechanism is mounted upon a rearwardly tilted, stepped frame 452, which is mounted upon a pair of supports 453 fixed upon the rear top surface of bed plate 3, the upper surfaces of which slope toward the rear of the machine, whereby spool frame 452 derives its rearward tilt, the particular purpose of which will be explained hereinafter. As seen in Figs. 1, 3, 15 3a and 32, spool frame 452 is formed with three substantially vertical steps at each side of its center, each of which is fitted with a row of three supply spool supports, so that there are six rows of three spools each, or eighteen spools altogether, whereby a maximum number of eighteen coils may be wound simultaneously upon the 20 winding spindle. Obviously, the number and arrangement of the supply spools may be altered as desired, and any part of the total number of spools may be utilized at one time as desired. By referring to Figs. 32 and 34, it is apparent that 25 the spools 454 are primarily mounted upon arbors 455 and centered thereon by cones 456 and 457, the latter being threaded upon arbors 455 so that they are removable for the purpose of removing the spool when it is exhausted and replacing it 30 with another full spool. Arbors 455 are freely rotatable upon a pair of ball bearings 458 mounted at the ends of rotatable axial sleeves 459 inserted in tubular bearings 460 which project inwardly through apertures in spool frame 452 and 35 are rigidly attached thereto. Sleeve 459 is journalled in the tubular bearing 460 and at one end is provided with a keeper collar 461 screwed onto the outside of sleeve 459, said sleeve being provided at its other end with a skew gear 462 40 staked thereto, so that upon the rotation of gear 462 sleeve 459 rotates in tubular bearing 460. The inner end of arbor 455 is pinned to a disc 463 against the surface of which a plurality of friction plugs 464, such as corks for example, 45 are adapted to bear, the corks being mounted in cups 465 disposed on a plate 466, so that the engagement of plugs 464 with disc 463 effectively brakes the rotation of the latter, and consequently the rotation of spool 454 as well. Plate 50 55 466 is mounted substantially upon gear 462 by means of a plurality of pins 467, such as the three shown in Fig. 35, the pins 467 being screwed into gear 462 and encircled by coil springs 468 which tend to keep the plate 466 away from the adjacent side of gear 462 and the friction plugs 464 on plate 466 disengaged from disc 463.
- The center of plate 466 is fitted with a hardened button 469 against the center of which impinges a pointed stud 470, which is fixed in a lever 471 pivoted upon a bracket 472 rigidly attached to the inner surface of spool frame 452, as shown in Figs. 32, 34 and 35. Lever 471 is also provided with a hardened button 473 against 60 the center of which impinges pointed stud 474, which is fixed in the end of a crank lever 475 journalled in a hub 476 disposed at the end of bracket 472, in the manner illustrated in Fig. 35. Pinned to the outer end of the axis of crank lever 475 is a flat plate 477 upon which is rigidly

5 mounted the end of a long lever 478, the other end of which is arranged so as to register vertically with an oval opening 479 in the top surface of spool frame 452, as shown in Fig. 32, in which the ends of the three levers of the three tiers of spools are visible through the openings 479. Attached to the ends of levers 478 and passing substantially vertically through openings 479, are a plurality of rods 480, the upper ends of which are attached to one end of pulley 10 levers 481, which are fulcrumed upon a rack 482 mounted upon standards 483 projecting from the upper surface of spool frame 452, and carry grooved pulley wheels 484. A number of coil springs 485 attached by one end to bars 486 fixed 15 to the bases of standards 483, are attached to rods 480 and tend to draw the latter downwardly so that levers 478 are in their lowest position, which effects the braking of spools 454.

The strand material, such as wire, passes from 20 its supply spools 454 over pulleys 484, over rollers 428 and under rollers 429 to the winding spindle, the tension of the wire pulling levers 481 downwardly against the tension of springs 485, which raises levers 479 to release friction plugs 464 from 25 discs 463, whereby spools 454 become freely rotatable and the wire may be unwound from them by being drawn from the spools by winding on to the winding spindle. Springs 485 are adjusted so that the proper wire tension is maintained, which 30 causes levers 481 to continually hunt. If the rotation of the winding spindle is stopped or one of the strands of wire breaks, the slack in the wire or breakage thereof causes springs 485 to pull rods 480 downwardly to effect the braking of the 35 spools or spool, and accordingly preventing overrunning and the consequent snarling and unwinding of the wire on the spools, which usually attain a considerable momentum. Accordingly, the proper wire tension is always maintained as 40 well as a tight winding upon the supply spools, which is necessary to prevent breakage by the jerking caused by loose or snarled wire upon the spools. The tensioning mechanism also causes the wire to be drawn tightly upon the winding 45 spindle, so that tight, firm and uniform finished coils are the result.

The spool frame is arranged so that all of the wire upon and passing from all of the supply spools is directly visible to the operator from his 50 station in front of the machine. Accordingly he can readily ascertain when a spool is nearly exhausted and must be replaced, and can immediately locate a broken strand, which latter is further indicated by the sudden sharp upward inclination of the pulley lever 481 over which the broken strand passed. Moreover, the spools, being arranged in stepped tiers upon overhung arbors, may be readily removed and replaced 55 from the sides of the machine without interfering with neighboring spools or the strands of wire passing therefrom and over the pulleys and guide rollers to the winding spindle. The spool frame is tipped rearwardly in the manner heretofore described, so that the spool arbors have a 60 slight upward tilt from the horizontal, in order to prevent the spool from falling or flying off of its arbor, should the spool retaining means suddenly fail. Nevertheless, the spool arbors are disposed very nearly horizontally so that the wire 65 will unwind evenly therefrom without snarling, which often results when the spools have too much inclination so that numerous convolutions of wire on the spool often slip axially so as to overlap or overlay the unwinding wire, and thus 70 75

cause snarling and the usually consequent jerking and breakage.

Occasionally during the winding operation, a strand may break or a spool may become suddenly exhausted whereupon the machine must be stopped and the defective strand repaired. For instance, in the winding of large coils more material is consumed, in consequence of which the strand material stored upon the supply spools must be frequently replenished and consequent frequent stops and splices must be made. Therefore, the machine must be adapted so that the shortest possible delay is necessary at each stop so as not to materially lessen the economy with which the winding operation can be performed. Hence, in the present machine, what is known as the back-winding operation is accomplished with the same facility as the winding operation, the backwinding being done for the purpose of unwinding from the winding spindle that portion of which is wound thereon before the machine is stopped upon the discovery of an end or imperfection in the strand. In other words, the machine must run backward with the same facility that it runs forward, and the reversal must be accomplished in the simplest manner and with the slightest manipulation on the part of the operator. Accordingly, the backwinding mechanism is driven by the same system that drives the forward winding mechanism and is dependent thereupon. By means of a reversing lever the backwinding mechanism is coupled to the same driving means that drives the winding spindle and both rotate in the reverse direction, the winding speeds of the spools and the spindle being arranged according to the diameter of the coils wound, the size of the wire, and the diameter of the spools, so that the peripheral velocities of the spools and the winding spindle are approximately the same, in order that the wire may be rewound upon the spools at the same rate that it is being unwound from the winding spindle to prevent breakage or other damage because of too much or too little wire tension. Accordingly, interchangeable gears are provided whereby the relation between the spindle and the spool speeds is approximately constant for both large and small coils, and the additional smaller variations in the arbor speeds are automatically compensated for by differences in diameter of the spindle and the spools as well as by the wire tensioning mechanism.

When the machine is winding coils, reversing lever 487 is set in the position shown most clearly in Figs. 1 and 2, and the spindle is driven forwardly, whereas the back winding mechanism is disconnected. Reversing lever 487 extends from the front to the rear of the machine directly beneath the bed plate 3 to which it is pivoted at 488, the handle end thereof projecting forwardly so that it may be readily grasped by the operator and moved into the other notch provided therefor in plate 489 attached to the front ledge of bed plate 3, as shown in Fig. 1. The movement of reversing lever 487 into its other notch in plate 489 effects the longitudinal movement of shifter shaft 490, which is slidably journaled in extensions of brackets 8, 9 and 326 and is attached to the rear end of lever 487 by means of fixed collar 491. The longitudinal movement of shifter shaft 490 to the right, as seen in Fig. 2, causes the angular movement of clutch lever 492 which is resiliently attached thereto, is fulcrumed to the under side of bed plate 3 and is bifurcated to engage sleeve 322,

to move sleeve 322 axially to the right as seen in Fig. 4a, which effects the disengagement of jaw clutch 321 and the engagement of jaw clutch 323. Accordingly, shaft 325 is driven in the reverse direction by shaft 7 through pinion 320, gear 493 mounted upon bracket 9, gear 494, which is pinned to one end of a countershaft 495 journaled in brackets 9 and 326, and to the other end of which is pinned a pinion 496, which in turn drives gear 329 and consequently shaft 10 325 which is keyed to sleeve 322 by keys 324. Gears 493, 494, 496 and 329 effect a considerably slower reverse drive than the heretofore described direct forward drive connection of shafts 7 and 325, and consequently, through pulley 330, belt 334 and pulley 333 of the head-stock, the winding spindle 354 rotates relatively slower in the reverse direction than it does in its forward or winding direction. This slower reverse rotation is communicated to countershaft 383 through gears 379, 380, 381 and 382 and thence to cam shaft 249 through gears 386 and 387. The reversal of the direction of rotation of cam shaft 249 obviously effects the reversal of the cycle of events it controls, namely the wire laying and guiding mechanism, whereby wire guide rod 424 and its attached guide rollers 428 and 429 is made to retrace its reciprocating movements to guide the wire unwinding from the winding spindle in the reverse manner in which it guided it as it was wound upon the winding spindle.

The longitudinal movement of shifter shaft 490, as seen in Fig. 2, also causes the angular movement of clutch lever 497 which is resiliently mounted on shaft 490, is fulcrumed to the under side of bed plate 3, and is bifurcated to engage the collar of jaw clutch 21, and thus causes its disengagement. The disengagement of jaw clutch 21 disconnects shaft 24 from the driving mechanism and consequently disconnects the paper feeding mechanism, which is primarily actuated thereby, and which accordingly remains stationary during the back winding operation, since no paper is required. The movement of shifter shaft 490 to the right, through levers 498 and 499 attached thereto and pivoted to the rear edge of bed plate 3, also effects the axial movement of spline collars 500 and 501, respectively, which are integral with double-nosed cams 250 and 247, respectively, and accordingly disengages them from their follower rollers 252 and 244, respectively. The disengagement of paper mechanism synchronizing cam 250 effects the forward position of stop lever 256 as seen in Fig. 7, so that the paper mechanism is stopped by the engagement of pin 130 upon gear 53 therewith for a moment after the paper mechanism is reconnected for operation by the shifting of lever 487 to the forward position, until the proper instant when the paper mechanism is automatically brought into synchronism with the rest of the machine by the action of reconnected cam 250. The disengagement of paper ejector cam 247 causes the paper ejector roll 144 to remain stationary during the back winding operation.

The longitudinal movement of shifter shaft 490 to the right, as seen in Fig. 4 also effects the angular movement of clutch lever 502, which is resiliently attached to shaft 490 by one end, fulcrumed upon the under side of bed plate 3, and bifurcated at the other end to engage the collar of half of jaw clutch 503 which keyed to driving shaft 7. This angular movement of lever 502 causes the engagement of jaw clutch 75

503, the other half of which carries bevel gear 504, which drives bevel pinion 505 attached to the extremity of a short vertical shaft 506 which is journaled in a tubular bracket 507 mounted on the top of bed plate 3. As shown in Fig. 4b, the upper end of shaft 506 is provided with a gear 508, which meshes with a gear 509 mounted upon one end of a short shaft 510 journaled in a tubular bracket 511 mounted upon the lower ledge of and projecting into spool frame 452. Gears 508 and 509 are interchangeable for the purpose heretofore disclosed, and, as shown in Fig. 4b, they are particularly applicable for use when relatively fine wire and small coils are being wound and a more rapid spool speed is required for back winding at the same rate as the winding spindle is paying off wire. By interchanging them a slower speed is obviously obtained which is particularly applicable when heavier wire and larger coils are being wound. Accordingly, the relation of gears 508 and 509 depends upon the character of the work being done.

The upper end of shaft 510 is provided with a bevel gear 512, as is shown in Figs. 4b, 32 and 33, with which mesh a pair of bevel gears 513 and 514, the former being pinned to and driving a horizontal shaft 515, and the latter being riveted to spur gears 516 and 517 and freely rotatable on shaft 515 between collars 518 pinned thereto, as is most clearly shown in Fig. 33. As seen in the schematic gear diagram of Fig. 36, the ends of shaft 515 are provided with spur gears 519, each of which drive two of the skew gears 462 of the middle row of supply spools 454, whereas the middle skew gears 462 of the middle row in turn drive spur gears 520 mounted on shaft 521, which in turn drive the top skew gears 462 of the middle row of supply spools, and thus the middle rows of spools 454 upon each side of the spool frame are driven in the opposite direction to that which they are rotated by the unwinding of wire therefrom during the coil winding process. The rotation of bevel gear 514, the direction of which is reversed with respect to bevel gear 513 and shaft 515, is again reversed when the motion transmitted to shafts 522 and 523 by gear 524 meshing with gear 516, and by gear 525 meshing with gear 517, respectively, whereby shafts 522 and 523 rotate simultaneously with and in the same direction as shafts 515 and 521. The ends of shaft 522 are provided with spur gears 526 which drive the lower two skew gears 462 of the rear rows of supply spools 454, and the middle skew gears 462 of the rear rows in turn drive spur gears 527 on the ends of shaft 528, which in turn drive the top skew gears of the rear rows of supply spools 454. In addition to spur gear 525, shaft 523 is provided with a spur gear 529 each of which drive the lower two skew gears 462 of the front rows of supply spools 454, and the middle skew gears 462 of the front rows in turn drive spur gears 530 on the ends of shaft 531, which in turn drive the top skew gears 462 of the front rows of supply spools 454. Obviously this geared reversing spool drive may be multiplied to drive a greater number of spools if desired.

In the manner heretofore described, the simultaneous reverse rotation of skew gears 462 effects the simultaneous reverse rotation of the supply spools 454, whereby the strands of wire which are simultaneously unwinding from the winding spindle due to its reverse rotation are being rewound upon the supply spools from which they had been drawn during the previous winding

process. As in the winding process, the wire tensioning mechanism operates to maintain the proper wire tension so that the wire is rewound evenly, smoothly and tightly upon the supply spools until the desired point in the prior winding process is attained for the purpose of making a splice in the wire in the case of breakage or exhaustion and replenishment of the wire supply. The constant hunting of the wire tensioning pulleys 484, caused by the varying pull of the wire, governs the braking of the spools, such that if the pull on a wire is excessive, pulley 484 is drawn downwardly sufficiently to effect the raising of friction plugs 464 from spool arbor friction disc 463, whereby the driving connection of the spool is severed and it comes to rest until the subsequent wire slack is sufficient to permit springs 485 to raise pulley 484 and recouple the backward driving means. Thus it will be seen that the proper predetermined wire tension is maintained during the back winding process as well as during winding process.

Having described the structure of the preferred machine embodying this invention in detail, the operation thereof will now be further explained. The selected winding spindle 354 is secured into the headstock and latched into the tail-stock, which is thrown upwardly from its disengaged position and automatically locked in its operative position where it engages and accordingly positions the other end of the spindle. The strands of wire or other material from the several supply spools 454 are led over their respective pulleys 484, over guide rollers 428 and under rollers 429 and attached to the core or stick of coils, such as primary coils, upon the winding spindle 354, as the case may be, and fastened thereto in the usual manner. Then carriage elevating bar 273 is adjusted with respect to scale 280 to the dimension graduated thereon equal to the thickness of one complete wound layer, which consists of the thickness of one layer of wire plus the thickness of the alternate layer of sheet material, which may be one of more complete wrappings thereof. By turning thumb-nut 277, pointer 279 is set upon scale 278 at the dimension equal to the starting diameter of the core or stick upon the winding spindle. In the manner heretofore described, the stop mechanism is set by revolving layer counter knob 284 until pointer 283 designates upon scale 282 the number of layers required for the finished coils, whereupon trip rod 291 is locked to rod 269 in the position where its end abuts trip lever 293, at which position clutch pulley 6 is disengaged from the power. Having done this, knob 284 is turned to bring scale 282 back to zero reading which retracts trip rod 291 from trip lever 293, which is accordingly later automatically tripped to stop the machine when it has wound the requisite number of layers previously set upon layer counter scale 282. The head-stock gears are set, the belt 334 and pulleys 330 and 333 are arranged to the proper driving speeds consistent with the character of the work, and the back-winding speed gears 508 and 509, shown in Fig. 4b, are also arranged to the proper back-winding speed. The number of wrappings per layer of sheet material having been determined, the requisite paper measuring cam 301, as seen in Figs. 7 and 9, is inserted and the type of sheet material required is chosen from the supply rolls 150 or 151 by switching the required webs 150^a or 151^b thereof, which are disposed upon guide aprons 178 or 179, respectively, into operative position so as to register with anvil 75.

129, which is done by grasping handle 198 and moving it either up or down. Assuming that the sheet material supplied by roll 150 is desired, the web 150^a thereof upon its guide apron 178 5 registers with anvil 129 and with the path of the paper carrying fingers 79 and 83.

The machine is started by throwing starting handle 10 downwardly which sets trip handle 18, and which causes the engagement of rotating 10 clutch band 14 with clutch pulley 6 to rotate the same and accordingly actuate the machine driving mechanism. The consequent rotation of winding spindle 354 winds up the attached strands of wire, which causes pulleys 484 to be 15 drawn downwardly to effect the release of supply spools 454 from brakes 464, and permits them to rotate freely as the wire is drawn off of them, but their rotation is immediately stopped by brakes 464 when the slack in the wire becomes 20 excessive or one of the wires breaks, whereupon pulleys 484 are drawn upwardly by springs 485. The paper feeding mechanism starts when it is released by the disengagement of stop lever 256 from pin 130 on gear 53 permitting the latter 25 to rotate which is accomplished by synchronizing cam 250 upon cam shaft 251 at the rear of the machine. The paper carrying arms 73 and 75 move upwardly from their extreme low position shown in Figs. 7 and 8, their fingers 79 and 83 30 embracing but not gripping the lateral edges of the web of sheet material until fingers 79 and 83 are released by the action of cam pawl 90 and latch 93 to grip the lateral edges of the web at a point below the leading edge of the web, the 35 point of gripping and the length of the forward projection of the web beyond the gripping points of the fingers being predetermined and effected by the particular shape of latch 93. Accordingly, the web is drawn taut and is carried relatively 40 slowly upwardly by the paper carrying arms 73 and 75 over anvil 129 and platen 217, against which latter it is smoothed and constrained by smoothing members 234 until a sufficient length thereof has been payed off to make the requisite 45 one or more wrappings around the core or stick plus a slight overlap, whereupon the arms 73 and 75 pause in the manner and for reasons heretofore explained, while roller 211 temporarily 50 presses the web against anvil 129 and knives 127 engage the edge of the latter to sever the measured sheet of material from the supply web. The sheet of proper length, having been severed from the supply web, is carried upwardly between platen 217 and smoothing members 234 by the 55 arms 73 and 75 to their topmost point of travel, at which the fingers are opened by the engagement of lug 148 with pin 81^a upon arm 73, whereupon the paper is deposited so that its forward projection is gripped to plate 145 by ejector roll 60 60, which was momentarily raised as the arms approached their top position. At the proper instant, ejector roll 144 is given its forward sliding impulse along plate 145 by ejector cam 241 on cam shaft 249 at the rear of the machine, 65 which applies the sheet of paper or other material tangentially to the winding stick or core 235, against which it is immediately caught and wrapped by the gripping action of the several strands of wire which are being wound thereon. 70 The paper carrying arms 73 and 75 are retracted with an uninterrupted quick-return motion to their nethermost position, as shown in Figs. 7 and 8, and knives 128 are retracted and roller 211 75 is raised from anvil 129, both latter actions being

effected respectively by cams 106 and 105 in the manner heretofore described.

The wire is laid in adjacent convolutions upon the stick 235 in layers by the reciprocating movement of guide bar 424, which movement, and consequently the length of the layers of wire is governed by the travel of pin 397 between spaced nuts 400 and 401, the positions of which are fixed when winding ordinary right cylindrical coils, the successive layers being all equal in length, but if 5 bobbin-shaped, pyramid or bank-wound coils are desired, the operator moves lever 432 so that pinions 402 and 430 engage, whereby the consequent rotation of left- and right-hand threaded rod 399 causes the spacing of nuts 400 and 401 to 10 be steadily decreased, which results in the decrease in length of the successive layers of wire to produce a coil of the above description. The engagement of pinions 402 and 430 may be effected either before the winding operation is 15 commenced or during and without interrupting the winding operation, and, if done during winding, a coil resembling a chamfered right cylinder is the product.

As the stick 235 is gradually increasing in diameter, due to the successive application of layers of wire and sheet material thereto, the carriage is being elevated at a rate proportional to the increasing diameter of stick, which rate is effected by the previously adjusted pitch of bar 213 disposed at the front of the machine, in order that the paper may be continually applied tangentially to the revolving stick from ejector plate 145. Likewise, as the carriage rises, the paper measuring mechanism, actuated by rack 296 and meshing pinion 297, effects an increase in the length of each successive sheet of paper to compensate for the increasing diameter of the stick, so that the predetermined wrapping or wrappings plus the lap may be maintained constant until the 40 winding is completed.

If during the winding operation the operator observes a broken strand or the ending of the wire upon a supply spool, he stops the machine by pressing down upon trip handle 18 which 45 unclutches the power. Then, in order to unwind those portions of the unbroken strands which were wound upon the spindle after the break in or the end of the single strand occurred and before the machine was stopped, the operator shifts reversing lever 487 into the other notch in plate 489, which causes the disconnection of the paper feeding and sheet ejecting mechanism, connects the back-winding mechanism to and reverses the spindle driving mechanism, and re- 50 verses the position of the reciprocating wire-laying mechanism, all in the manners heretofore described in detail. Upon throwing starting handle 10 downwardly which re-clutches the power to the machine, the winding spindle and the 60 several supply spools 454 are dependently driven in the reverse direction whereby the spindle pays off the wire wound thereon, which is thereupon rewound upon the supply spools 454. When this back winding has continued until the perfect 65 strands are unwound to the point where the break occurred in the defective winding or where the wound wire ended, the machine is again stopped by striking handle 18, and the broken wire is quickly spliced, or a new wire attached 70 to the end of the wound wire, as the case may be. Reversing lever 487 is then returned to its forward position and the forward winding operation is resumed. In the splicing operation, a few turns may be imparted to the winding spin- 75

idle by manually turning head-stock cone pulley 333 for the purpose of bringing the spindle in a more convenient position for splicing.

- If, during the winding operation, the operator observes that the sheet of paper is crumpled, torn or twisted in transit for some reason or another, so that it cannot be applied properly to the winding stick, he stops the machine, and, by manipulating hand-wheel 36, he can manually replace the damaged sheet with another sheet of the same length without interfering with the other mechanism of the machine, and the synchronizing mechanism will automatically return the paper carrying arms, which have been manually disturbed, into their proper position with reference to the paper feeding cycle. Thus a perfect finished product is assured, and all of the layers of wire are separated by an interposed layer of sheet material, which may be of uniform material throughout the entire stick of coils or it may be changed during the winding operation. Accordingly, a plurality of sources of sheet material supply is furnished, as by the supply rolls 150 and 151 shown in Fig. 3, any one of which may be readily selected during and without interrupting the winding process. For example, the first and last few layers of all of the coils of the winding can be served, if desired, with heavy paper, oiled linen, silk, or the like, and the intervening layers may be served with an insulating paper adequate for the purpose, which is accomplished selectively while maintaining the spindle speed and without interrupting the feed or causing wrinkling or other irregularities in the sheet material, notwithstanding the fact that exceedingly thin material may be used. The switching of the sheet material from one type to another, during and without interrupting or before the winding operation, is done by pulling up or pushing down on lever 198 at the base of the machine, which lever is locked in position until released at the proper instant by the action of cam 104, in the manner and for purpose heretofore described. The plurality of sheet material supply sources may be all of one kind, if only one kind is used in the winding process, so that a full roll may be switched to replace an exhausted roll during and without interrupting the winding process.
- The machine is automatically stopped upon the completed winding of the desired number of layers, the number having been predetermined and set upon layer counter scale 282. Inasmuch as the movement of rod 269 toward the right, as seen in Fig. 1, during the progression of the winding process, moves attached trip rod 291 with it, the engagement of trip rod 291 with trip lever 293 of trip handle 18 effects the stopping of the machine when the required number of layers, to which the stop mechanism has been set, have been wound. When the winding operation is completed, knob 445 of the tail-stock is pulled axially to disengage winding spindle bearing 441 from the winding spindle 354, and tail-stock arm 442 is thrown backwardly out of the way. After disconnecting the several strands of wire from the completed stick of coils, the winding spindle is detached from the head-stock and removed, whereupon the stick of completed coils is stripped or drawn from the winding spindle. The winding spindle is inserted into a new core or stick and replaced in the machine, the carriage of which has been returned to the starting position by manually bringing dial 282 to its zero reading which, by means of knob 284, shaft 265,

pinion 268, rod 269 and arm 271, causes roller 272 to retrace its path down elevating bar 273 to its initial position, which consequently lowers the carriage to its starting point. Simultaneously with the lowering of the carriage, the paper measuring mechanism is returned to its starting point in readiness for measuring the length of the first layer of sheet material to be wound upon the new succeeding core or stick upon the winding spindle, inasmuch as the paper measuring mechanism driving pinion 297 retraces its movement down fixed rack 296, which, accordingly reverses the prior movement of pinions 299 and 300 and paper measuring cam 301, since they are all pinned together. Simultaneously with the lowering of the carriage, the sheet material forward projection length measuring and maintaining mechanism is returned to its original starting position, and which comprises pawl 93 fixed to lever 91, which is actuated by the linkage consisting of a lever 309 and link 313 upon shaft 310, and link 316 attached to cam pin 314 and to pillow block 318. If the successive layer-contracting mechanism is being utilized, the reverse movement imparted to shaft 265, as the carriage is lowered, reverses the direction of the former rotation of pinions 402 and 430, as well as the former direction of rotation of right- and left-hand threaded rod 399, thereby causing the outward movement of stop nuts 400 and 401 to increase their spacing to the original starting dimension. The machine is then in readiness for repeating the multiple coil winding operation heretofore described in detail.

While this specification and the accompanying drawings describe and illustrate the preferred embodiment of this invention, it is to be understood that changes may be freely made in the design, arrangement and dimensions of its several complementary parts without departing from the spirit of the invention within the scope of the appended claims.

What is claimed is:

1. In a winding machine, a winding spindle, means for winding sheet material on said spindle, a plurality of independently revoluble holders for sheet material, selective means operable to place the material on any of said holders in operative position independently of unselected material of the other holders, and means to supply strand material to the sheet material being wound.

2. In a winding machine, a plurality of sheet material supply rolls, means adapted to selectively extract sheet material from any of said rolls independently of unselected material during and without interrupting the winding process, and means to wind strand material with said sheet material.

3. In a winding machine, a plurality of holders of individual supplies of sheet material, a displaceable support provided with guides for a plurality of different sheets of material, means to retain said support with one guide positioned to place one of said sheets in operative position, and means for switching said support to displace said guide and sheet and to place another guide and sheet in operative position.

4. In a winding machine, the combination of a winding spindle, means for continuously winding a windable body on said spindle, means for intermittently winding a second windable body on said spindle, a plurality of sources for supplying said second body, and means for select-

- ing any of said sources during and without interrupting the winding process.
5. In a winding machine, the combination of a winding spindle, means for continuously winding alternate layers of strand and sheet material upon said spindle, independent high speed means for driving said spindle and consisting of a belt and pulley system, and independent low speed means for driving said spindle selectively in a forward or reverse direction and consisting of gearing.
6. In a winding machine, the combination of a winding spindle, strand material supply spools, means for continuously winding layers of strand material upon said spindle, independent high speed means for driving said spindle and consisting of a belt and pulley system, independent low speed means for driving said spindle and consisting of a belt and pulley and gearing combination, and means dependent upon said means for reversing the direction of rotation of said spindle and said strand material supply spools.
7. In a winding machine, the combination of a winding spindle, means for winding strand and sheet material in combination thereon, gearing and pulley means for driving said spindle, and means for shifting said gearing and pulley means to obtain other speeds.
8. In a machine for winding sheet material, the combination of a winding spindle, means for winding sheets thereon, a pivoted carriage for serving sheets to said spindle, carriage elevating means, and paper measuring means, said paper measuring means including propulsion means actuated by said carriage elevating means.
9. In a machine for winding sheet material, the combination of a winding spindle, means for winding sheets thereon, a paper serving carriage, means for moving said carriage at a rate proportional to the rate of diameter increase of the winding on said spindle, measuring means for increasing the length of successive sheets, and propelling means actuated by said carriage for variously positioning said measuring means.
45. 10. In a machine for winding sheet material, the combination of a winding spindle, means for severing sheets from a continuous web, a sheet support, pivoted gripper means for drawing the sheets over said support, means for constraining the sheets to said support, and means for presenting the sheets to said spindle.
11. In a machine for winding sheet material, the combination of a winding spindle, a platen, pivotal means for drawing a continuous web of sheet material over said platen, means for severing a sheet from the web, means for temporarily stopping said pivotal means during the severing operation, means for periodically increasing the length of successive severed sheets, and independent means for constraining the severed sheets to said platen.
60. 12. In a machine for winding sheet material, the combination of a winding spindle, means for gripping the sides of the material, a curved platen, means for moving said gripping means in an arcuate path whereby the material is drawn taut over said platen, means for constraining the material to said platen, means for severing the material at a predetermined length, and ejector means adapted to receive the leading edge of the severed material from said gripping means, said ejector means being adapted to apply the severed material to said spindle.
70. 13. A machine for winding sheet material comprising a plurality of members for gripping the leading lateral edges of a continuous web of sheet material, means for pivoting said members, a support for the sheet material, cutters for severing sheets from said web, a winding spindle, and means for presenting the sheets to said winding spindle.
14. In a machine for winding sheet material, the combination of a winding spindle, means for severing sheets from a continuous web of sheet material, a support for the sheets, pivotal means for drawing the sheets arcuately over said support, and means for transferring the sheets from said support to said spindle.
15. In a machine for winding sheet material, the combination of a winding spindle, sheet length measuring mechanism, sheet severing mechanism, sheet carrying mechanism, pivotally mounted adjacent said winding spindle and an arcuate support for the sheet during transit, and a transfer mechanism for presenting the sheet to said spindle.
16. In a machine for winding sheet material, the combination of a winding spindle, a sheet carrying mechanism comprising a pair of oscillatory gripping arms, and a transfer mechanism adapted to receive the sheet from said carrying mechanism and feed the same to said spindle.
17. In a machine for winding sheet material, the combination of a winding spindle, a pair of gripping arms bodily movable to convey the sheet toward the spindle, a support for the sheet during transit, and an ejector mechanism for receiving the sheet from said arms and thereafter feeding the sheet to said spindle.
35. 18. In a machine for winding sheet material, the combination of a winding spindle, a cutting mechanism for severing sheets from a continuous web, a pair of oscillatory arms adapted to convey a sheet from said cutting mechanism toward said spindle, a support for the sheet during transit, and an ejector mechanism for receiving the sheet from said arms and thereafter feeding the same to said spindle.
19. In a machine for winding sheet material, the combination of a winding spindle, carrying mechanism comprising gripping members, means for closing said members to grip the lateral edges of the sheet material while in one position, means for bodily moving said members to move the sheet material, means for supporting the sheet material in transit, means for opening said members to release the sheet material when in another position, and transfer means for feeding the sheet material to said spindle.
50. 20. In a machine for winding sheet material, the combination of a winding spindle, means for severing sheets from a continuous web, means for increasing the lengths of successive sheets, a sheet support, means for gripping and drawing the sheets over said support toward said spindle, and means for presenting the sheets to said spindle.
55. 21. In a machine for winding sheet material, a winding spindle, means for winding sheets thereon, sheet carrying mechanism comprising a pair of oscillatory members, grippers upon said members, said grippers adapted to effect a lateral movement upon closure, and means for transferring the sheets from said grippers to said spindle.
60. 22. In a winding machine, the combination of a winding spindle, means for feeding sheet material thereto comprising a plurality of oscillatory members having grippers thereon, a common
70. 75. 75

shaft for actuating said members, and an oscillatory mechanism for actuating said shaft.

23. In a winding machine, the combination of a winding spindle, means for feeding sheet material thereto comprising a plurality of oscillatory members, and reversing mechanism for actuating said members, said mechanism adapted to move said members relatively slowly in one direction and effect a quick return thereof in the opposite direction.

24. In a winding machine, the combination of a winding spindle, means for feeding sheet material thereto comprising a plurality of pivotal members, reciprocating means for actuating said members slowly in one direction and rapidly the other direction.

25. In a winding machine, the combination of a winding spindle, a tilting carriage independent thereof, means including a plurality of pivotally mounted grippers for feeding sheet material to said spindle, means for progressively tilting said carriage, and means whereby the tilt of said carriage determines the length of the sheet material to be fed.

26. In a winding machine, the combination of a winding spindle, a carriage independent thereof, means carried by said carriage for feeding sheet material to said spindle, settable means for maintaining said carriage in a position whereby the sheet material is fed tangentially to material on said spindle, and indicating means for predeterminedly adjusting said settable means in accordance with winding requirements.

27. In a winding machine, the combination of a winding spindle, means for feeding sheet material thereto comprising pivotal arms, and a driven crank for moving said arms slowly in one direction and rapidly in the opposite direction.

28. In a winding machine, the combination of a winding spindle, means for feeding sheet material thereto comprising oscillatory arms, gripping means on said arms, a driven shaft mounting said arms, and means whereby the rotation of said shaft effects the opening and closing of said gripping means.

29. In a winding machine, the combination of a winding spindle, means for feeding sheet ma-

terial thereto comprising pivotal members, grippers on said members adapted to impart a lateral tension to the sheet material, and means for intermittently moving said members in one direction and uninterruptedly in the other direction.

30. In a winding machine, the combination of a winding spindle, means for feeding sheet material thereto comprising pivotal members, means for actuating said members, a progressively tilting carriage mounting said members, a stop mechanism for temporarily halting said members, and means actuated by the movement of said carriage for progressively re-positioning said stop mechanism.

31. In a winding machine, a winding spindle, a traverse member, a shaft for imparting motion to said member, reversing mechanism for reversing the direction of rotation of said shaft, means for feeding a sheet of paper to said spindle, a knife operable to cut said sheet into pre-determined lengths and a common means for controlling said reversing mechanism and controlling the operation of said knife.

32. In a machine for winding sheet material, the combination of a winding spindle, a sheet supply web, oscillatory means for gripping the lateral edges of said web, means for moving said oscillatory means, means for temporarily stopping said oscillatory means at a definite length of web, means for severing said web at said length, a platen for supporting the severed sheet, means for smoothing the sheet to said platen, and ejector means for receiving the sheet from said oscillatory means, said ejector means adapted to apply the sheet to said spindle.

33. In a winding machine, a winding spindle, a frame pivoted at its rear end and having its forward end adjacent said spindle, material feeding means mounted on said frame adjacent said spindle, a carriage supporting the forward end of the frame, means for moving the carriage, and means responsive to a movement of the carriage for imparting a pivotal movement to said frame.

ANNIE G. ANDERSON, 45
*Executrix of the Estate of James C. Anderson,
Deceased.*
